(57) **ABSTRACT**

A wisdom ring puzzle includes: a stage; a first ring unit positioned in a first direction with respect to the stage; a second ring unit positioned in the first direction with respect to the first ring unit; a first pole and a second pole connected to the second ring unit and connected to the stage through the inner side of the first ring unit. The first pole is connected to the first ring unit, extends in the first direction from the first ring unit, turns and extends in a second direction opposite to the first direction, is connected to the stage passing through the inner side of the first ring unit, and passes through the inner side of the second ring unit at a side of the first direction of the first ring unit.

WISDOM RING PUZZLE

**CROSS REFERENCE TO RELATED
APPLICATIONS**

This application claims the benefit of priority to Japanese Patent Application No. 2021-178353, filed on Oct. 29, 2021, the entire contents of which are incorporated herein by reference.

FIELD

An embodiment of the present invention relates to a wisdom ring puzzle. More specifically, an embodiment of the present invention relates to a wisdom ring puzzle having a three-dimensional structure including a pole and a ring member which can be enjoyed using a looped lace.

BACKGROUND

As represented by the Chinese ring, there is known a wisdom ring puzzle composed of a rod-shaped pole, a ring member arranged at a tip of the pole, and a looped lace. In recent years, a wisdom ring puzzle composed of a combination of a pole and a ring member using the Chinese ring as a prototype has been proposed (U.S. Pat. No. 6,112,956 and Japanese laid-open patent publication No. H2-283392). Further, U.S. Pat. No. 6,546,364 is proposed as a wisdom ring puzzle having a different structure from that of the Chinese ring. The wisdom ring puzzle according to U.S. Pat. No. 6,546,364 is a puzzle having a three-dimensional structure and uses a looped lace.

The wisdom ring puzzle described in U.S. Pat. No. 6,112,956 and Japanese laid-open patent publication No. H2-283392 is complicated to solve, but there are many repetitions of simple mechanical operations, so that there are few stimuli to the logical thinking and imagination of a player. Therefore, there is a problem in that the player cannot have a contiguous interest and motivation to create a solution for these wisdom ring puzzles.

SUMMARY

A wisdom ring puzzle according to an embodiment includes: a stage; a first ring unit positioned in a first direction with respect to the stage; a second ring unit positioned in the first direction with respect to the first ring unit; a first pole; and a second pole connected to the second ring unit and connected to the stage through the inner side of the first ring unit. The first pole is connected to the first ring unit, extends in the first direction from the first ring unit, turns and extends in a second direction opposite to the first direction, is connected to the stage passing through the inner side of the first ring unit, and passes through the inner side of the second ring unit at a side of the first direction of the first ring unit.

The second pole may extend toward the stage from an end portion of the second ring unit in the second direction. The second pole may be connected to the stage.

The wisdom ring puzzle may further include: a third ring unit positioned between the stage and the first ring unit; and a third pole connected to the third ring unit and connected to the stage. The first pole may be connected to the stage through the inner side of the third ring unit.

The stage may include a stage upper surface, the first pole, the second pole, and the third pole being connected to the stage upper surface. The first ring unit may be arranged on

2

a first virtual plane. The second ring unit may be arranged on a second virtual plane. The third ring unit may be arranged on a third virtual plane. An angle formed by the stage upper surface and the first virtual plane may be smaller than an angle formed by the stage upper surface and the second virtual plane. An angle formed by the stage upper surface and the third virtual plane may be smaller than an angle formed by the stage upper surface and the second virtual plane.

10 The wisdom ring puzzle may further include: a third ring unit positioned in the first direction with respect to the first ring unit; a fourth ring unit positioned in the first direction with respect to the third ring unit; a third pole; and a fourth pole connected to the fourth ring unit and connected to the stage through the inner side of the third ring unit. The third pole may be connected to the third ring unit, may extend in the first direction from the third ring unit, may turn and extend in the second direction, and may pass through the inner side of the third ring unit and the inner side of the first ring unit. The first pole may pass through the inner side of the second ring unit. The third pole may pass through inner side of the fourth ring unit.

The stage may include a stage upper surface, the first pole, the second pole, and the third pole being connected to the stage upper surface. The first ring unit may be arranged on a first virtual plane. The second ring unit may be arranged on a second virtual plane. The third ring unit may be arranged on a third virtual plane. The fourth ring unit may be arranged on a fourth virtual plane. An angle formed by the stage upper surface and the first virtual plane may be smaller than an angle formed by the stage upper surface and the second virtual plane. An angle formed by the stage upper surface and the third virtual plane may be smaller than an angle formed by the stage upper surface and the second virtual plane. An angle formed by the stage upper surface and the fourth virtual plane may be smaller than an angle formed by the stage upper surface and the third virtual plane. An angle formed by the stage upper surface and the first virtual plane may be smaller than an angle formed by the stage upper surface and the fourth virtual plane. An angle formed by the stage upper surface and the third virtual plane may be smaller than an angle formed by the stage upper surface and the fourth virtual plane.

45 The wisdom ring puzzle may further include: a third ring unit positioned in the first direction with respect to the first ring unit; a fourth ring unit positioned in the first direction with respect to the third ring unit; a third pole; and a fourth pole. The third pole may be connected to the third ring unit, may extend in the first direction from the third ring unit, may turn and extend in the second direction, and may pass through the inner side of the third ring unit. The fourth pole may be connected to the fourth ring unit, may extend in the first direction from the fourth ring unit, may turn and extend in the second direction, and may be connected to the stage through the inner side of the third ring unit and the inner side of the first ring unit. The first pole may pass through the inner side of the second ring unit. The third pole may pass through the inner side of the fourth ring unit.

50 The stage may include a stage upper surface, the first pole, the second pole, and the third pole being connected to the stage upper surface. The first ring unit may be arranged on a first virtual plane. The second ring unit may be arranged on a second virtual plane. The third ring unit may be arranged on a third virtual plane. The fourth ring unit may be arranged on a fourth virtual plane. An angle formed by the stage upper surface and the first virtual plane may be smaller than an angle formed by the stage upper surface and the second virtual plane. An angle formed by the stage upper surface and the third virtual plane may be smaller than an angle formed by the stage upper surface and the second virtual

plane. An angle formed by the stage upper surface and the first virtual plane may be smaller than an angle formed by the stage upper surface and the fourth virtual plane. An angle formed by the stage upper surface and the third virtual plane may be smaller than an angle formed by the stage upper surface and the fourth virtual plane.

The second pole may extend in the first direction from an end portion of the second ring unit in the first direction, may turn and extend in the second direction, and may be connected to the stage through the inner side of the first ring unit.

The wisdom ring puzzle may further include: a third ring unit positioned between the stage and the first ring unit; and a third pole connected to the third ring unit and connected to the stage. The second pole may be connected to the stage through the inner side of the third ring unit.

The stage may include a stage upper surface, the first pole, the second pole, and the third pole being connected to the stage upper surface. The first ring unit may be arranged on a first virtual plane. The second ring unit may be arranged on a second virtual plane. The third ring unit may be arranged on a third virtual plane. An angle formed by the stage upper surface and the first virtual plane may be smaller than an angle formed by the stage upper surface and the second virtual plane. An angle formed by the stage upper surface and the third virtual plane may be smaller than an angle formed by the stage upper surface and the second virtual plane.

A wisdom ring puzzle according to an embodiment includes: a stage; a first ring unit positioned in a first direction with respect to the stage; a second ring unit positioned in the first direction with respect to the first ring unit; a first pole; a second pole; and a third pole. The first pole is connected to the first ring unit, extends in the first direction from the first ring unit, turns and extends in a second direction opposite to the first direction, is connected to the stage, and passes through the inner side of the second ring unit. The second pole is connected to the second ring unit, extends in the first direction from the second ring unit, turns and extends in the second direction, and is connected to the stage. The third pole is connected to the stage, extends in the first direction from the stage, turns and extends in the second direction, and passes through the inner side of the first ring unit. A gap is provided between an end portion of a part of the third pole in the second direction and the stage. The part extends in the second direction.

A position where the first pole is connected to the stage may be arranged between a position where the second pole is connected to the stage and the second ring unit in a plan view. The second ring unit may be arranged between a position where the first pole is connected to the stage and the first ring unit in a plan view.

The first ring unit may be arranged between a position where the second pole is connected to the stage and the second ring unit in a plan view. The second ring unit may be arranged between a position where the first pole is connected to the stage and the first ring unit in a plan view.

A wisdom ring puzzle according to an embodiment includes: a stage; a first ring unit positioned in a first direction with respect to the stage; a second ring unit positioned in the first direction with respect to the first ring unit; a first pole; a second pole; and a third pole. The first pole is connected to the first ring unit, extends in the first direction from the first ring unit, turns and extends in a second direction opposite to the first direction, is connected to the stage crossing over the outer side of the first ring unit, and passes through the inner side of the second ring unit at

a side of the first direction of the first ring unit. The second pole is connected to the second ring unit, extends in the first direction from the second ring unit, turns and extends in the second direction, and is connected to the stage. The third pole is connected to the stage, extends in the first direction from the stage, turns and extends in the second direction, and passes through the inner side of the first ring unit. A gap is provided between an end portion of a part of the third pole in the second direction and the stage, the part extending in the second direction.

A position where the first pole is connected to the stage may be arranged between a position where the second pole is connected to the stage and the second ring unit in a plan view. The second ring unit may be arranged between a position where the first ring unit is connected to the first pole and a position where the first pole is connected to the stage in a plan view.

A position where the first ring unit is connected to the first pole may be arranged between a position where the second pole is connected to the stage and the second ring unit in a plan view. The second ring unit may be arranged between a position where the first ring unit is connected to the first pole and a position where the first pole is connected to the stage in a plan view.

BRIEF DESCRIPTION OF DRAWINGS

FIG. 1A is a diagram showing a structure of a wisdom ring puzzle according to an embodiment of the present invention.

FIG. 1B is a diagram showing a structure of a wisdom ring puzzle according to an embodiment of the present invention.

FIG. 2 is a diagram showing a method of solving a wisdom ring puzzle according to an embodiment of the present invention.

FIG. 3 is a diagram showing a method of solving a wisdom ring puzzle according to an embodiment of the present invention.

FIG. 4 is a diagram showing a method of solving a wisdom ring puzzle according to an embodiment of the present invention.

FIG. 5 is a diagram showing a method of solving a wisdom ring puzzle according to an embodiment of the present invention.

FIG. 6A is a diagram showing a structure of a wisdom ring puzzle according to an embodiment of the present invention.

FIG. 6B is a diagram showing a structure of a wisdom ring puzzle according to an embodiment of the present invention.

FIG. 7 is a diagram showing a method of solving a wisdom ring puzzle according to an embodiment of the present invention.

FIG. 8 is a diagram showing a method of solving a wisdom ring puzzle according to an embodiment of the present invention.

FIG. 9A is a diagram showing a structure of a wisdom ring puzzle according to an embodiment of the present invention.

FIG. 9B is a diagram showing a structure of a wisdom ring puzzle according to an embodiment of the present invention.

FIG. 10 is a diagram showing a method of solving a wisdom ring puzzle according to an embodiment of the present invention.

FIG. 11 is a diagram showing a method of solving a wisdom ring puzzle according to an embodiment of the present invention.

FIG. 12 is a diagram showing a structure of a wisdom ring puzzle according to an embodiment of the present invention.

FIG. 13 is a diagram showing a method of solving a wisdom ring puzzle according to an embodiment of the present invention.

FIG. 14 is a diagram showing a method of solving a wisdom ring puzzle according to an embodiment of the present invention.

FIG. 15 is a diagram showing a method of solving a wisdom ring puzzle according to an embodiment of the present invention.

FIG. 16 is a diagram showing a method of solving a wisdom ring puzzle according to an embodiment of the present invention.

FIG. 17 is a diagram showing a structure of a wisdom ring puzzle according to an embodiment of the present invention.

FIG. 18 is a diagram showing a method of solving a wisdom ring puzzle according to an embodiment of the present invention.

FIG. 19 is a diagram showing a method of solving a wisdom ring puzzle according to an embodiment of the present invention.

FIG. 20 is a diagram showing a method of solving a wisdom ring puzzle according to an embodiment of the present invention.

FIG. 21 is a diagram showing a method of solving a wisdom ring puzzle according to an embodiment of the present invention.

FIG. 22A is a diagram showing a structure of a wisdom ring puzzle according to an embodiment of the present invention.

FIG. 22B is a diagram showing a structure of a wisdom ring puzzle according to an embodiment of the present invention.

FIG. 23 is a diagram showing a structure of a wisdom ring puzzle in a comparative example.

DESCRIPTION OF EMBODIMENTS

Hereinafter, a wisdom ring puzzle according to the present embodiment will be described in detail with reference to the drawings. In the following description, elements having substantially the same functions and configurations are denoted by the same symbols and will be described redundantly only when necessary. The following embodiments exemplifies a device and method for embodying the technical idea of this embodiment. The technical idea of the embodiment is not to specify the material, shape, structure, arrangement, or the like of the constituent parts as follows. Various modifications may be made to the technical idea of the embodiment in addition to the scope of the claims.

In each embodiment of the present invention, direction from a stage 100 toward each structure body (e.g., a first structure body 200) is referred to as upper direction or first direction. On the contrary, direction from each structure toward the stage 100 is referred to as lower direction or second direction. As described above, for convenience of explanation, although the phrase "upper" or "lower" is used for explanation, for example, the stage 100 and the first structure body 200 may be arranged so that the vertical relationship is opposite to the drawing. In the following description, for example, the expression "the first structure body 200 above the stage 100" merely describes the vertical relationship between the stage 100 and the first structure body 200 as described above, and other members may be arranged between the stage 100 and the first structure body 200. The upper direction or lower direction means the vertical relationship in a vertical direction in the plurality of members, and the expression "the first structure body

200 above the stage 100" indicates the positional relationship in which the stage 100 and the first structure body 200 do not overlap in a plan view. On the other hand, the expression "the first structure body 200 vertically above the stage 100" indicates the positional relationship in which the stage 100 and the first structure body 200 overlap in a plan view.

In the present specification, expressions " α includes A, B, or C," " α includes any of A, B, and C," and " α includes one selected from a group consisting of A, B, and C," do not exclude the case where α includes a plurality of combinations of A to C unless otherwise specified. Furthermore, these expressions do not exclude the case where α includes other elements.

An object of an embodiment of the present invention is to provide a wisdom ring puzzle capable of sustaining the interest and motivation of a player to create a solution.

1. First Embodiment

Wisdom ring puzzles 10 and 10A according to a first embodiment of the present invention will be described with reference to FIG. 1A to FIG. 5. FIG. 1A and FIG. 1B are diagrams illustrating structures of wisdom ring puzzles according to embodiments of the present invention. FIG. 2 to FIG. 5 are diagrams showing a method of solving a wisdom ring puzzle according to an embodiment of the present invention. As will be described later, the wisdom ring puzzles 10 and 10A are puzzles using laces 20 and 20A. The player enjoys the wisdom ring puzzles 10 and 10A by entangling the laces 20 and 20A with poles (for example, third poles 420 and 420A) arranged on the wisdom ring puzzles 10 and 10A or removing the laces 20 and 20A from the poles.

[1-1. Structure of Wisdom Ring Puzzle 10]

As shown in FIG. 1A, the wisdom ring puzzle 10 includes the stage 100, the first structure body 200, a second structure body 300, and a third structure body 400. The lace 20 is used to play with the wisdom ring puzzle 10. In the present embodiment, although the lace 20 has a closed loop shape, it is not limited to this configuration.

The stage 100 includes an upper surface 101 and a bottom surface 103. The first structure body 200, the second structure body 300, and the third structure body 400 are connected to the upper surface 101. The bottom surface 103 is a surface that can be placed on a flat surface such as a table. In the present embodiment, the stage 100 has a circular flat plate shape in a plan view. However, the shape of the stage 100 in a plan view is not limited to a circular shape. For example, the shape of the stage 100 in a plan view may be a polygon such as a triangle or a quadrangle or may be an ellipse or a looped curved shape. In addition, the upper surface 101 and the bottom surface 103 are not limited to a flat surface and may be a structure in which unevenness is arranged.

The first structure body 200 includes a first ring unit 210 and a first pole 220. The first ring unit 210 is arranged on a virtual plane substantially parallel to the upper surface 101. The first pole 220 is connected to the first ring unit 210 and has an upwardly convex U-shape. In other words, the first pole 220 is connected to the first ring unit 210, extends in direction D1 from a connection part with the first ring unit 210, is turned, and extends in direction D2. The first pole 220 extending in the direction D2 passes through the inner side of the first ring unit 210 and reaches the stage 100. The first pole 220 is connected to the first ring unit 210 at an end portion of the first ring unit 210 in direction D4 in a plan

view. In a plan view, the first pole **220** extends in direction D3 from the connection part with the first ring unit **210** and reaches the stage **100** at the inner side of the first ring unit **210**. However, a position where the first pole **220** is connected to the first ring unit **210** is not limited to the above-described configuration.

The second structure body **300** includes a second ring unit **310** and a second pole **320**. The second ring unit **310** is arranged on a virtual plane substantially orthogonal to the upper surface **101**. The second pole **320** extends from an end portion of the second ring unit **310** in the direction D2 toward the stage **100** and is connected to the stage **100**. However, a position where the second pole **320** is connected to the second ring unit **310** is not limited to the above-described configuration.

The third structure body **400** includes a third ring unit **410** and the third pole **420**. The third ring unit **410** is arranged on a virtual plane substantially parallel to the upper surface **101**. The third pole **420** is connected to the third ring unit **410** at an end portion of the third ring unit **410** in the direction D3. The third pole **420** extends from a connection part with the third ring unit **410** toward the direction D2 and is connected to the stage **100**. However, a position where the third pole **420** is connected to the third ring unit **410** is not limited to the above-described configuration.

The first ring unit **210** is positioned in the direction D1 with respect to the stage **100**. The second ring unit **310** is positioned in the direction D1 with respect to the first ring unit **210**. The third ring unit **410** is positioned in the direction D1 with respect to the stage **100** and the direction D2 with respect to the first ring unit **210**. As described above, in the present embodiment, the virtual plane (first virtual plane) on which the first ring unit **210** is arranged and the virtual plane (third virtual plane) on which the third ring unit **410** is arranged are substantially parallel to the upper surface **101**, and the virtual plane (second virtual plane) on which the second ring unit **310** is arranged is substantially orthogonal to the upper surface **101**. However, the present invention is not limited to the above configuration. For example, the angle formed by the upper surface **101** and the first virtual plane and the angle formed by the upper surface **101** and the third virtual plane may be smaller than the angle formed between the upper surface **101** and the second virtual plane.

In the present embodiment, although the configuration in which all of the second ring units **310** are positioned in the direction D1 with respect to the first ring unit **210** is exemplified, the configuration is not limited to this configuration. For example, a part of the second ring unit **310** may be positioned in the direction D1 with respect to the first ring unit **210**. That is, when viewed from the side, the first ring unit **210** and the second ring unit **310** may intersect.

The first pole **220** extends in the direction D1 from the connection part with the first ring unit **210**, passes through the inner side of the second ring unit **310**, and then passes through the inner side of the first ring unit **210** in the direction D2. Further, the first pole **220** passes through the inner side of the first ring unit **210** in the direction D2, passes through the inner side of the third ring unit **410**, and is connected to the stage **100**. In a plan view, the first pole **220** extends from the connection part with the first ring unit **210** toward the third pole **420** (the direction D3), passes through the inner side of the second ring unit **310**, and is connected to the stage **100** at a position where the first ring unit **210** and the third ring unit **410** overlap. The second pole **320** extends from the second ring unit **310** in the direction D2, passes through the inner side of the first ring unit **210**, and is

connected to the stage **100**. The third pole **420** extends from the third ring unit **410** in the direction D2 and is connected to the stage **100**.

In the present embodiment, the first ring unit **210**, the second ring unit **310**, and the third ring unit **410** are contiguous with the first pole **220**, the second pole **320**, and the third pole **420**, respectively. For example, the first ring unit **210** is formed such that the first pole **220** is bent and forms a ring shape on the first virtual plane. Therefore, in the wisdom ring puzzle **10** of the present embodiment, each ring unit is not a completely closed loop shape without a gap but may be a closed loop shape without a gap. Also, even when a gap is arranged in each ring unit in the present embodiment, a width of the gap is such that the lace **20** does not pass therethrough. In addition, in the present embodiment, the first ring unit **210** and the first pole **220** are contiguous rod-shaped members. Similarly, the second ring unit **310** and the second pole **320** are contiguous rod-shaped members. Similarly, the third ring unit **410** and the third pole **420** are contiguous rod-shaped members. However, the ring unit and the pole may be separate members, and they may be joined to each other by welding or the like.

[1-2. Structure of Wisdom Ring Puzzle 10A]

As shown in FIG. 1B, a wisdom ring puzzle **10A** includes a stage **100A**, a first structure body **200A**, a second structure body **300A**, and a third structure body **400A**. Although the wisdom ring puzzle **10A** shown in FIG. 1B is similar to the wisdom ring puzzle **10** shown in FIG. 1A, the first structure body **200A** and the second structure body **300A** are different from the first structure body **200** and the second structure body **300** of the wisdom ring puzzle **10**. In the following description, differences between the wisdom ring puzzle **10** and the wisdom ring puzzle **10A** will be mainly explained. In the following description, in the case of describing the same configuration as the wisdom ring puzzle **10**, the description may be omitted by adding the letter "A" after the symbols shown in FIG. 1A.

A second pole **320A** extends in the direction D1 from an end portion of the second ring unit **310A** in the direction D1, turns and extends in the direction D2. The second pole **320A** extending in the direction D2 passes through the inner side of each of a first ring unit **210A** and a third ring unit **410A** and reaches the stage **100A**. In a plan view, the second pole **320A** extends from a connection part with the second ring unit **310A** toward a third pole **420A** (the direction D3) and is connected to the stage **100A** at a position crossing over a first pole **220A** and at a position where the first ring unit **210A** and the third ring unit **410A** overlap.

Although the second ring unit **310** is positioned at the uppermost portion in the wisdom ring puzzle **10** shown in FIG. 1A, the second pole **320A** is positioned at the uppermost portion in the wisdom ring puzzle **10A** shown in FIG. 1B. Further, the wisdom ring puzzle **10** is different from the wisdom ring puzzle **10A** in that the first pole **220** passes through each of the inner sides of the first ring unit **210** and the third ring unit **410** in the wisdom ring puzzle **10** while the second pole **320A** passes through each of the inner sides of the first ring unit **210A** and the third ring unit **410A** in the wisdom ring puzzle **10A**.

In FIG. 1A and FIG. 1B, although the configuration in which the first poles **220** and **220A** pass through the inner side of the second ring units **31** and **310A** in the vicinity of the uppermost portion of the first poles **220** and **220A** is exemplified, the configuration is not limited to this. The first poles **220** and **210A** may pass through the inner side of the second ring units **310** and **310A** from a connection part between the first ring units **210** and **210A** and the first poles

220 and 220A to the position where the first poles 220 and 220A pass through the inner side of the first ring units 210 and 210A in the direction D2. Therefore, for example, the second virtual plane on which the second ring units 310 and 310A are arranged may be parallel to the first virtual plane on which the first ring units 210 and 210A are arranged.

[1-3. Method of Solving Wisdom Ring Puzzle 10 (Part 1)]

A method 1000 of solving the wisdom ring puzzle 10 shown in FIG. 1A will be described with reference to FIG. 2. The lace 20 is used to play the wisdom ring puzzle 10. The player moves the lace 20 along the poles (the first pole 220 to the third pole 420) arranged on the first structure body 200 to the third structure body 400 and moves the lace 20 between the poles by passing it through the inner side of the ring units (the first ring unit 210 to the third ring unit 410) or crossing it over the outer side of the ring units. Then, in the present embodiment, the player aims for a state in which the lace 20 is entangled only with the third pole 420. That is, the wisdom ring puzzle 10 according to the present embodiment is a puzzle that aims at a state in which only the third pole 420 exists at the inner side of the lace 20.

As shown in (A) of FIG. 2, a tip 21 of the lace 20 passes through the inner side of the first ring unit 210 in the direction D1 (1) and passes through the inner side of the second ring unit 310 in the direction D4 (2). In this case, the tip 21 moves along the first pole 220 and passes through the second ring unit 310 at the area in the direction D1 with respect to the first pole 220. In this state, the lace 20 does not pass through the inner side of the third ring unit 410. The lace 20 which passed through the inner side of the second ring unit 310 sandwiches the first pole 220.

As shown in (B) of FIG. 2, the tip 21 of the lace 20 moves upward along the first pole 220, crosses over the second ring unit 310 in the direction D3 (3), moves along the first pole 220 in the direction D2 (4), and passes through the inner side of the first ring unit 210 in the direction D2 (5).

As shown in (C) of FIG. 2, the tip 21 of the lace 20 crosses over the outer side (direction D3 side) of the first ring unit 210 in the direction D1 (6) and crosses over the second ring unit 310 in the direction D4 (7). That is, the lace 20 hangs on the inner side of the second ring unit 310 and hangs down in the direction D2. In this state, the lace 20 sandwiches the first pole 220. Also, the tip 21 of the lace 20 may pass through the inner side of the first ring unit 210. This is the difference between the state shown in (A) of FIG. 2 and the state shown in (C) of FIG. 2.

As shown in (D) of FIG. 2, the tip 21 of the lace 20 passes through the inner side of the second ring unit 310 in the direction D3 (8), passes through the inner side of the first ring unit 210 in the direction D2 (9), moves in the direction D2 along the first pole 220, and crosses over the outer side (direction D4 side) of the third ring unit 410 in the direction D2. As a result, the lace 20 is in a state of being entangled with the first pole 220 and the third pole 420. In this state, the first pole 220 and the third pole 420 exist on the inner side of the lace 20.

As shown in (E) of FIG. 2, the tip 21 of the lace 20 passes through the inner side of the third ring unit 410 in the direction D1 (10), passes through the inner side of the first ring unit 210 in the direction D1 (11), and passes through the inner side of the second ring unit 310 in the direction D4 (12). That is, the lace 20 hangs on the inner side of the second ring unit 310 and hangs down in the direction D2 so as to pass through the inner side of the first ring unit 210. In this state, the lace 20 sandwiches the first pole 220 and the third pole 420. A point that the lace 20 passes through the

inner side of the third ring unit 410 is a difference between the state shown in (C) of FIG. 2 and the state shown in (E) of FIG. 2.

As shown in (F) of FIG. 2, from a state in which the tip 21 of the lace 20 passes through the inner side of the first ring unit 210 in the direction D2, while maintaining a state in which the lace 20 sandwiches the first ring unit 210, the tip 21 moves in the direction D1, crosses over the outer side (direction D4 side) of the first ring unit 210 in the direction D1 (13), moves in the direction D1 along the first pole 220, crosses over the second ring unit 310 in the direction D3 (14), moves in the direction D2 along the first pole 220 (15), and crosses over the outer side (direction D3 side) of the first ring unit 210 in the direction D2 (16).

As shown in (G) of FIG. 2, the tip 21 of the lace 20 passes through the inner side of the first ring unit 210 in the direction D1 (17) and crosses over the second ring unit 310 in the direction D4 (18). The lace 20 crosses over the second ring unit 310 and sandwiches the first pole 220. The tip 21 is positioned further in the direction D4 with respect to the first pole 220 than the connection part between the first pole 220 and the first ring unit 210. This is the difference between the state shown in (E) of FIG. 2 and the state shown in (G) of FIG. 2.

As shown in (H) of FIG. 2, the tip 21 of the lace 20 passes through the inner side of the second ring unit 310 in the direction D3 (19), passes through the inner side of the first ring unit 210 in the direction D2 (20), and passes through the inner side of the third ring unit 410 in the direction D2 (21). As a result, the lace 20 is in a state of being entangled only with the third pole 420. In this state, only the third pole 420 exists at the inner side of the lace 20. That is, this state is a state in which the puzzle is solved.

[1-4. Method of Solving Wisdom Ring Puzzle 10 (Part 2)]

Another method 1000 of solving the wisdom ring puzzle 10 shown in FIG. 1A will be described with reference to FIG. 3. As shown in (A) of FIG. 3, the tip 21 of the lace 20 passes through the inner side of the third ring unit 410 in the direction D1 (1), passes through the inner side of the first ring unit 210 in the direction D1 (2), and passes through the inner side of the second ring unit 310 in the direction D4 (3). In this case, the tip 21 moves along the first pole 220 and passes through the second ring unit 310 at the area in the direction D1 with respect to the first pole 220. In this state, the lace 20 which passed through the inner side of the second ring unit 310 sandwiches the first pole 220.

As shown in (B) of FIG. 3, the tip 21 of the lace 20 moves in the direction D1 along the first pole 220, crosses over the second ring unit 310 in the direction D3 (4), moves in the direction D2 along the first pole 220 (5), and passes through the inner side of the first ring unit 210 in the direction D2 (6).

As shown in (C) of FIG. 3, the tip 21 of the lace 20 crosses over the outer side (direction D3 side) of the first ring unit 210 in the direction D1 (7), and crosses over the second ring unit 310 in the direction D4 (8). That is, the lace 20 hangs on the inner side of the second ring unit 310 and hangs down in the direction D2. In this state, the lace 20 sandwiches the first pole 220. Also, the tip 21 of the lace 20 may pass through the inner side of the first ring unit 210. This is the difference between the state shown in (A) of FIG. 3 and the state shown in (C) of FIG. 3.

As shown in (D) of FIG. 3, the tip 21 of the lace 20 passes through the inner side of the second ring unit 310 in the direction D3 (9), passes through the inner side of the first ring unit 210 in the direction D2 (10), moves along the first pole 220 in the direction D2, and passes through the inner side of the third ring unit 410 in the direction D2 (11). As a

11

result, the lace 20 is in a state of being entangled only with the first pole 220. In this state, only the first pole 220 exists at the inner side of the lace 20.

As shown in (E) of FIG. 3, the tip 21 of the lace 20 passes through the inner side of the first ring unit 210 in the direction D1 (12) and passes through the inner side of the second ring unit 310 in the direction D4 (13). In this case, the tip 21 passes through the first ring unit 210 at the area in the direction D4 with respect to the first pole 220. That is, the lace 20 hangs on the inner side of the second ring unit 310 and hangs down in the direction D2 so as to pass through the inner side of the first ring unit 210. In this state, the lace 20 sandwiches the first pole 220 at the side of the direction D2 of the third ring unit 410. In this state, a point that the lace 20 crosses over the outer side of the third ring unit 410 (does not pass through the inner side of the third ring unit 410) is a difference between the state shown in (C) of FIG. 3 and the state shown in (E) of FIG. 3.

As shown in (F) of FIG. 3, the tip 21 of the lace 20 crosses over the outer side (direction D2 side) of the first ring unit 210 in the direction D1 while maintaining a state in which the lace 20 sandwiches the first ring unit 210 (14), moves in the direction D1 along the first pole 220, crosses over the second ring unit 310 in the direction D3 (15), moves in the direction D2 along the first pole 220 (16), and crosses over the outer side (direction D3 side) of the first ring unit 210 in the direction D2 (17).

As shown in (G) of FIG. 3, the tip 21 of the lace 20 passes through the inner side of the first ring unit 210 in the direction D1 (18), and crosses over the second ring unit 310 in the direction D4 (19). The lace 20 which crossed over the second ring unit 310 sandwiches the first pole 220. The tip 21 is positioned further in the direction D4 with respect to the first pole 220 than the connection part between the first pole 220 and the first ring unit 210. This is the difference between the state shown in (E) of FIG. 3 and the state shown in (G) of FIG. 3.

As shown in (H) of FIG. 3, the tip 21 of the lace 20 passes through the inner side of the second ring unit 310 in the direction D3 (20), passes through the inner side of the first ring unit 210 in the direction D2 (21), and the lace 20 is reversed in the direction D3 to be entangled only with the third pole 420 (a state in which the puzzle is solved). In this state, only the third pole 420 exists at the inner side of the lace 20.

[1-5. Method of Solving Wisdom Ring Puzzle 10A (Part 1)]

A method 1000A of solving the wisdom ring puzzle 10A shown in FIG. 1B will be described with reference to FIG. 4. The wisdom ring puzzle 10A is a puzzle targeting a state in which a lace 20A is entangled only with the third pole 420A (a state in which only the third pole 420A exists at the inner side of the lace 20A) similar to the wisdom ring puzzle 10.

First, the lace 20A is arranged so that the first structure body 200A to a third structure body 400A are all positioned at the inner side of the lace 20A. That is, in a state where the lace 20A is placed on the stage 100A, the first pole 220A to the third pole 420A are sandwiched (surrounded) by the lace 20A. From that state, as shown in (A) of FIG. 4, a tip 21A of the lace 20A passes through the inner side of the first ring unit 210A in the direction D1 (1), passes through the inner side of the second ring unit 310A in the direction D4 (2), and passes through the inner side of the first ring unit 210A in the direction D2 (3). In this case, the tip 21A passes through the first ring unit 210A at the area in the direction D4 with

12

respect to the first pole 220A and passes through the second ring unit 310A at the area in the direction D2 with respect to the first pole 220A.

As shown in (B) of FIG. 4, the tip 21A of the lace 20A extending in the side of the direction D2 of the first ring unit 210A crosses over the outer side (direction D4 side) of the first ring unit in the direction D1 (4), moves in the direction D1 along the first pole 220A and the second pole 320A, and crosses over the uppermost portion of the second pole 320A in the direction D3 (5). Thereafter, the tip 21A moves in the direction D2 along the second pole 320A and crosses over the outer side (direction D3 side) of the first ring unit 210A in the direction D2 (6). In this state, the lace 20A in the vicinity of the tip 21A sandwiches the first pole 220A and the second pole 320A and is positioned at the outer side of the first ring unit 210A.

As shown in (C) of FIG. 4, the tip 21A of the lace 20A passes through the inner side of the first ring unit 210A in the direction D1 (7), crosses over the uppermost portion of the second pole 320A in the direction D4 (8), moves in the direction D2 along the second pole 320A and the first pole 220A, and crosses over the outer side (direction D4 side) of the first ring unit 210A in the direction D2 (9). In this state, the lace 20A in the vicinity of the tip 21A sandwiches the first pole 220A and the second pole 320A and is positioned at the outer side of the first ring unit 210A.

As shown in (D) of FIG. 4, the tip 21A of the lace 20A passes through the inner side of the second ring unit 310A in the direction D3 (10) and passes through the inner side of the first ring unit 210A in the direction D2 (11). As a result, the lace 20A is in a state of being entangled with the second pole 320A and the third pole 420A. In this state, the second pole 320A and the third pole 420A exist on the inner side of the lace 20A.

As shown in (E) of FIG. 4, the tip 21A of the lace 20A passes through the inner side of the third ring unit 410A in the direction D1 (12), passes through the inner side of the first ring unit 210A in the direction D1 (13), and passes through the inner side of the second ring unit 310A in the direction D4 (14). That is, the lace 20A hangs on the inner side of the second ring unit 310A and hangs down in the direction D2. In this state, the lace 20A sandwiches the first pole 220A, the second pole 320A, and the third pole 420A. As in (C) of FIG. 4, the lace 20A in the vicinity of the tip 21A is positioned at the outer side of the first ring unit 210A. In this state, a point that the lace 20A passes through the inner side of the third ring unit 410A is a difference between the state shown in (C) of FIG. 4 and the state shown in (E) of FIG. 4.

As shown in (F) of FIG. 4, the tip 21A of the lace 20A moves in the direction D1 along the first pole 220A and the second pole 320A and crosses over the uppermost portion of the second pole 320A in the direction D3 (15). Thereafter, the tip 21A moves in the direction D2 along the second pole 320A (16).

As shown in (G) of FIG. 4, the tip 21A of the lace 20A passes through the inner side of the first ring unit 210A (an area between the first ring unit 210A and the second pole 320A) in the direction D2 (17), turns and crosses over the outer side (direction D3 side) of the first ring unit 210A in the direction D1 (17). The tip 21A moves in the direction D1 along the second pole 320A, crosses over the uppermost portion of the second pole 320A in the direction D4 (18), moves in the direction D2 along the second pole 320A and the first pole 220A, and passes through the inner side of the first ring unit 210A in the direction D2 (19). That is, the lace 20A hangs on the inner side of the second ring unit 310A and

hangs down in the direction D2 so as to pass through the inner side of the first ring unit 210A. In this state, the lace 20A sandwiches the first pole 220A, the second pole 320A, and the third pole 420A. In this state, a point that the lace 20A passes through the inner side of the first ring unit 210A is a difference between the state shown in (E) of FIG. 4 and the state shown in (G) of FIG. 4.

As shown in (H) of FIG. 4, the tip 21A of the lace 20A passes through the inner side of the first ring unit 210A in the direction D1 (20), moves in the direction D1 along the first pole 220A, passes through the second ring unit 310A in the direction D3 (21), moves in the direction D2 along the first pole 220A, and passes through the inner side of the first ring unit 210A in the direction D2 (22). Thereafter, the tip 21A crosses over the outer side (direction D4 side) of the first ring unit 210A in the direction D1 (23), moves in the direction D1 along the first pole 220A and the second pole 320A, and crosses over the uppermost portion of the second pole 320A in the direction D3 (24), moves in the direction D2 along the second pole 320A, and crosses over the outer side (direction D3 side) of the first ring unit 210A in the direction D2 (25), so that the lace 20A is in a state of being entangled only with the third pole 420A (a state in which the puzzle is solved). In this state, only the third pole 420A exists at the inner side of the lace 20A.

[1-6. Method of Solving Wisdom Ring Puzzle 10A (Part 2)]

Another method 1000A of solving the wisdom ring puzzle 10 shown in FIG. 1B will be described with reference to FIG. 5. As shown in (A) of FIG. 5, the tip 21A of the lace 20A passes through the inner side of the third ring unit 410A in the direction D1 (1), passes through the inner side of the first ring unit 210A in the direction D1 (2), and passes through the inner side of the second ring unit 310A in the direction D4 (3). In this state, the lace 20A which passed through the inner side of the second ring unit 310A sandwiches the first pole 220A.

As shown in (B) of FIG. 5, the tip 21A of the lace 20A moves in the direction D4 with respect to the first ring unit 210A in the direction D1 along the first pole 220A and the second pole 320A (4), crosses over the uppermost portion of the second pole 320A in the direction D3 (5), moves in the direction D2 along the second pole 320A, and passes through the inner side of the first ring unit 210A in the direction D2 (6).

As shown in (C) of FIG. 5, the tip 21A of the lace 20A crosses over the outer side (direction D3 side) of the first ring unit 210A in the direction D1 (7), moves in the direction D1 along the second pole 320A, crosses over the uppermost portion of the second pole 320A in the direction D4 (8), moves in the direction D2 along the second pole 320A and the first pole 220A, and passes through the inner side of the first ring unit 210A in the direction D2 (9). That is, the lace 20A hangs on the inner side of the second ring unit 310A and hangs down in the direction D2. In this state, the lace 20A sandwiches only the first pole 220A.

As shown in (D) of FIG. 5, the tip 21A of the lace 20A passes through the inner side of the first ring unit 210A in the direction D1 (10), passes through the inner side of the second ring unit 310A in the direction D3 (11), and passes through the inner side of the first ring unit 210A in the direction D2 (12). As a result, the lace 20A is in a state of being entangled only with the first pole 220A and passing through the inner side of the third ring unit 410A.

As shown in (E) of FIG. 5, the tip 21A of the lace 20A crosses over the side of the direction D4 of the first ring unit 210A, moves in the direction D1 along the first pole 220A and the second pole 320A (13), crosses over the uppermost

portion of the second pole 320A in the direction D3 (14), and moves in the direction D2 along the second pole 320A (15). As a result, the lace 20A is in a state of being entangled only with the second pole 320A. In this state, only the second pole 320A exists at the inner side of the lace 20A.

As shown in (F) of FIG. 5, the tip 21A of the lace 20A crosses over the outer side (direction D4 side) of the third ring unit 410A in the direction D1, passes through the inner side of the first ring unit 210A in the direction D1 (16), moves in the direction D1 along the first pole 220A, and passes through the inner side of the second ring unit 310A in the direction D4 (17). That is, the lace 20A hangs on the inner side of the second ring unit 310A and hangs down in the direction D2. In this state, the lace 20A in the vicinity of the tip 21A sandwiches the first pole 220A and is positioned at the outer side of the first ring unit 210A. A point that the lace 20A does not pass through the inner side of the third ring unit 410A (crosses over the outer side of the third ring unit 410A) and a point that the lace 20A sandwiches the first pole 220A are differences between the state shown in (A) of FIG. 5 and the state shown in (F) of FIG. 5.

As shown in (G) of FIG. 5, the tip 21A of the lace 20A crosses over the uppermost portion of the second pole 320A in the direction D3 (18), moves in the direction D2 along the second pole 320A, and passes through the inner side of the first ring unit 210A in the direction D2 (19).

As shown in (H) of FIG. 5, the tip 21A of the lace 20A crosses over the outer side (direction D3 side) of the first ring unit 210A in the direction D1 (20), moves in the direction D1 along the second pole 320A, crosses over the uppermost portion of the second pole 320A (21), moves in the direction D2 along the second pole 320A and the first pole 220A, and crosses over the outer side (direction D4 side) of the first ring unit 210A (22). In this state, the lace 20A is in a state of being entangled with the first pole 220A and the second pole 320A.

From this state, the tip 21A of the lace 20A moves in the reverse order of the above (20) to (22). That is, the tip 21A crosses over the outer side (direction D4 side) of the first ring unit 210A in the direction D1, moves in the direction D1 along the first pole 220A and the second pole 320A, crosses over the uppermost portion of the second pole 320A in the direction D3, moves in the direction D2 along the second pole 320A, and crosses over the outer side (direction D3 side) of the first ring unit 210A in the direction D2. As a result, the lace 20A is in a state of being entangled only with the third pole 420A (a state in which the puzzle is solved). In this state, only the third pole 420A exists at the inner side of the lace 20A.

2. Second Embodiment

Wisdom ring puzzles 10B and 100 according to the second embodiment will be described with reference to FIG. 5A to FIG. 8. FIG. 6A and FIG. 6B are diagrams illustrating structures of wisdom ring puzzles according to embodiments of the present invention. FIG. 7 to FIG. 8 are diagrams showing a method of solving a wisdom ring puzzle according to an embodiment of the present invention. As in the first embodiment, the wisdom ring puzzles 10B and 100 are puzzles using laces 20B and 20C. The player enjoys the wisdom ring puzzles 20B and 20C by entangling the laces with the poles (for example, second poles 320B and 320C) arranged on the wisdom ring puzzles 10B and 100 or removing the laces from the poles. In the following description, description of the same configuration as that of the wisdom ring puzzle 10 of the first embodiment will be

omitted. In the following description, in the case of describing the same configuration as the wisdom ring puzzle 10, the description may be omitted by adding the letters "B" or "C" after the symbols shown in FIG. 1A.

[2-1. Structure of Wisdom Ring Puzzle 10B]

As shown in FIG. 6A, the wisdom ring puzzle 10B includes a stage 100B, a first structure body 200B, a second structure body 300B, and a third structure body 400B.

The first structure body 200B includes a first ring unit 210B and a first pole 220B. The first ring unit 210B is arranged on a first virtual plane substantially orthogonal to an upper surface 101B. The first pole 220B is connected to the first ring unit 210B and has an upwardly convex U-shape. In other words, the first pole 220B is connected to the first ring unit 210B, extends in the direction D1 from a connection part with the first ring unit 210B, turns, extends in the direction D2, and reaches the stage 100B.

The second structure body 300B includes a second ring unit 310B and the second pole 320B. The second ring unit 310B is arranged on a second virtual plane substantially orthogonal to the upper surface 101B. The second pole 320B is connected to the second ring unit 310B and has an upwardly convex U-shape. In other words, the second pole 320B is connected to the second ring unit 310B, extends in the direction D1 from the connection part with the second ring unit 310B, turns, extends in the direction D2, and reaches the stage 100B.

The third structure body 400B includes a third pole 420B. The third pole 420B has an upwardly convex U-shaped shape. In other words, the third pole 420B is connected to the stage 100B, extends in the direction D1 from the stage 100B, turns and extends in the direction D2. A gap is arranged between a tip 430B of the third pole 420B extending in the direction D2 and the stage 100B.

The first ring unit 210B is positioned in the direction D1 with respect to the stage 100B. The second ring unit 310B is positioned in the direction D1 with respect to the first ring unit 210B. As described above, in the present embodiment, the first virtual plane on which the first ring unit 210B is arranged and the second virtual plane on which the second ring unit 310B is arranged are substantially orthogonal to the upper surface 101B. That is, the first virtual plane and the second virtual plane are parallel to each other. However, the relationship between the first and second virtual planes and the upper surface 101B is not limited to the above configuration.

The first ring unit 210B is arranged in the direction D4 with respect to the first pole 220B. The second ring unit 310B is arranged in the direction D4 with respect to the second pole 320B. The tip 430B is arranged in the direction D3 with respect to a position where the third pole 420B is connected to the stage 100B. That is, although the first pole 220B and the second pole 320B are folded back in the same direction (direction D4), the third pole 420B turns in the direction (direction D3) opposite to the first pole 220B and the second pole 320B.

The above configuration will be described in detail. The first pole 220B extends in the direction D1 from the connection part with the first ring unit 210B and is connected to the stage 100B after passing through the inner side of the second ring unit 310B in the direction D3. In a plan view, the first pole 220B extends in the direction D3 from the connection part with the first ring unit 210B and is connected to the stage 100B at a position between where the second pole 320B is connected to the stage 100B and the second ring unit 310B. The second pole 320B extends in the direction D1 from the second ring unit 310B and is connected to the stage

100B at a position opposite to the first ring unit 210B and the third pole 420B in a plan view. The third pole 420B extends in the direction D1 from the stage 100B and passes through the inner side of the first ring unit 210B in the direction D3. Therefore, in a plan view, the tip 430B is connected to the stage 220B at a position between where the first pole 220B is connected to the stage 100B and the first ring unit 210B.

In other words, in a plan view, the position where the first pole 220B is connected to the stage 100B is positioned between the position where the second pole 320B is connected to the stage 100B and the second ring unit 310B. The second ring unit 310B is positioned between a position where the first pole 220B is connected to the stage 100B and the first ring unit 210B.

[2-2. Structure of Wisdom Ring Puzzle 100]

As shown in FIG. 6B, the wisdom ring puzzle 100 includes a stage 100C, a first structure body 200C, a second structure body 300C, and a third structure body 400C. The wisdom ring puzzle 100 shown in FIG. 6B is similar to the wisdom ring puzzle 10B shown in FIG. 6A, but the directions of the first structure body 200C and the third structure body 400C are different from the first structure body 200B and the third structure body 400B of the wisdom ring puzzle 10B. In the following description, the difference between the wisdom ring puzzle 10B and the wisdom ring puzzle 100 will be mainly explained. In the following description, in the case of describing the same configuration as the wisdom ring puzzle 10B, the description may be omitted by adding the letter "C" instead of the letter "B" after the symbols shown in FIG. 6A.

As shown in FIG. 6B, in the wisdom ring puzzle 100, the directions of the first structure body 200C and the third structure body 400C are opposite to the directions of the first structure body 200B and the third structure body 400B in FIG. 6A. That is, a first ring unit 210C is arranged in the direction D3 with respect to a first pole 220C. A tip 430C is arranged in the direction D4 with respect to a position where a third pole 420C is connected to the stage 100C. That is, although the second pole 320C and the third pole 420C are folded back in the same direction (direction D4) after extending in the direction D1 from the stage 100C, the first pole 220C turns in the direction (direction D3) opposite to the second pole 320C and the third pole 420C.

The above configuration will be described in detail. In a plan view, the first pole 220C extends in the direction D4 from the connection part with the first ring unit 210C and is connected to the stage 100C at a position further in the direction D4 than the second ring unit 310C. In a plan view, the second pole 320C extends in the direction D3 from the connection part with the second ring unit 310C and is connected to the stage 100C at a position crossing over the first ring unit 210C and the third pole 420C (direction D3) side of the first ring unit 210C and the third pole 420C.

In other words, in a plan view, the first ring unit 210C is positioned between a position where the second pole 320C is connected to the stage 100C and the second ring unit 310C. The second ring unit 310C is positioned between a position where the first pole 220C is connected to the stage 100C and the first ring unit 210C.

In FIG. 6A and FIG. 6B, although a configuration in which the first poles 220B and 220C pass through the inner side of the second ring units 310B and 310C in the vicinity of the uppermost portion of the first poles 220B and 220C, it is not limited to this configuration. The first poles 220B and 220C may pass through the inner side of the second ring units 310B and 310C from the connection part between the first ring units 210B and 210C and the first poles 220B and

220C to the position where the first poles 100B and 100C connect to the first pole 220B. Therefore, for example, the second virtual plane on which the second ring units 310B and 310C are arranged may be parallel to the upper surface 101B of the stage 100B. Similarly, it is sufficient that the third poles 420B and 420C pass through the inner side of the first ring units 210B and 210C, and the first virtual plane arranged with the first ring units 210B and 210C may be parallel to the upper surface 101B.

[2-3. Method of Solving Wisdom Ring Puzzle 10B]

A method 1000B of solving the wisdom ring puzzle 10B shown in FIG. 6A will be described with reference to FIG. 7. The wisdom ring puzzle 10B is a puzzle targeting a state in which the lace 20B is entangled only with the second pole 320B (a state in which only the second pole 320B exists at the inner side of the lace 20B).

First, the lace 20B is arranged so that the first structure body 200B to the third structure body 400B are all positioned on the inner side of the lace 20B. That is, in a state where the lace 20B is placed on the stage 100B, the first pole 220B to the third pole 420B are sandwiched (surrounded) by the lace 20B. From that state, as shown in (A) of FIG. 7, a tip 21B of the lace 20B passes through the inner side of the first ring unit 210B in the direction D3 (1), crosses over the lower side of the tip 430B in the direction D4 (2), and passes through the inner side of the first ring unit 210B in the direction D4 (3). According to this operation, a state in which only the first pole 220B and the second pole 320B exist on the inner side of the lace 20B can be obtained.

As shown in (B) of FIG. 7, the tip 21B of the lace 20B moves upward along the first pole 220B, passes through the inner side of the second ring unit 310B in the direction D4 (4), and crosses over the lower side of the tip 430B in the direction D4 (5).

As shown in (C) of FIG. 7, the tip 21B of the lace 20B crosses over the lower side of the first ring unit 210B in the direction D4, turns and passes through the inner side of the first ring unit 210B in the direction D3 (6).

As shown in (D) of FIG. 7, the tip 21B of the lace 20B crosses over the lower side of the tip 430B in the direction D3 (7), moves upward along the third pole 420B, and passes through the inner side of the first ring unit 210B in the direction D4 (8). In this state, the lace 20B sandwiches the first ring unit 210B from the outer side of the first ring unit 210B.

As shown in (E) of FIG. 7, the tip 21B of the lace 20B moves in the direction D1 on the outer side (direction D4 side) of the first ring unit 210B, moves in the direction D1 along the first pole 220B, and passes through the inner side of the second ring unit 310B in the direction D3 (9). According to the operation (9) described above, the lace 20B is in a state of being entangled only with the second pole 320B (a state in which the puzzle is solved). In this state, only the second pole 320B exists at the inner side of the lace 20B.

[2-4. Method of Solving Wisdom Ring Puzzle 100]

A method 1000C of solving the wisdom ring puzzle 100 shown in FIG. 6B will be described with reference to FIG. 8. The wisdom ring puzzle 100 is a puzzle targeting a state in which a lace 20C is entangled only with the second pole 320C (a state in which only the second pole 320C exists at the inner side of the lace 20C) like the wisdom ring puzzle 10B.

As shown in (A) of FIG. 8, a tip 21C of the lace 20C passes through the inner side of the second ring unit 310C in the direction D3 (1), moves downward along the first pole 220C, and passes through the inner side of the first ring unit

210C in the direction D4 (2). In this state, the lace 20C sandwiches the first pole 220C.

As shown in (B) of FIG. 8, the tip 21C of the lace 20C crosses over the lower side of the tip 430C in the direction D3 (3) and passes through the inner side of the first ring unit 210C in the direction D3 (4). Although the state shown in (B) of FIG. 8 is similar to the state shown in (A) of FIG. 8, it is different in that the lace 20C is entangled with the third pole 420C.

As shown in (C) of FIG. 8, the tip 21C of the lace 20C crosses over the outer side (direction D2 side) of the first ring unit 210C in the direction D4 and crosses over the side of the direction D2 of the tip 430C in the direction D4 (5).

As shown in (D) of FIG. 8, the tip 21C of the lace 20C moves upward along the first pole 220C, passes through the inner side of the second ring unit 310C in the direction D4 (6), and moves downward along the first pole 220C. In this state, the lace 20C is in a state of being entangled only with the first pole 220C. That is, only the first pole 220C exists at the inner side of the lace 20C.

As shown in (E) of FIG. 8, the tip 21C of the lace 20C moves in the direction D1 along the third pole 420C, passes through the inner side of the first ring unit 210C in the direction D4, and crosses over the side of the direction D2 of the tip 430C in the direction D4 (7).

As shown in (F) of FIG. 8, the tip 21C of the lace 20C passes through the inner side of the first ring unit 210C in the direction D3 (9) and moves downward along the third pole 420C. In this state, the lace 20C is in a state of being entangled with the first pole 220C and the third pole 420C. That is, the first pole 220C and the third pole 420C exist on the inner side of the lace 20C.

As shown in (G) of FIG. 8, while the position of the tip 21C of the lace 20C is maintained between the second pole 320C and the third pole 420C, the other end (not shown) of the lace 20C moves in the direction D1 along the first pole 220C and the second pole 320C (10), crosses over the uppermost portion of the second pole 320C in the direction D3 (10), and moves in the direction D2 along the second pole 320C (10). According to this operation, the lace 20C is in a state of being entangled only with the second pole 320C (a state in which the puzzle is solved). In this state, only the second pole 320C exists at the inner side of the lace 20C.

3. Third Embodiment

The wisdom ring puzzles 10D and 10E according to the third embodiment will be described with reference to FIG. 9A to FIG. 11. FIG. 9A and FIG. 9B are diagrams illustrating structures of wisdom ring puzzles according to embodiments of the present invention. FIG. 10 to FIG. 11 are diagrams showing a method of solving a wisdom ring puzzle according to an embodiment of the present invention. As in the first and second embodiments, the wisdom ring puzzles 10D and 10E are puzzles using laces 20D, and 20E. The player enjoys the wisdom ring puzzles 20D and 20E by entangling the laces with the poles (for example, second poles 320D and 320E) arranged on the wisdom ring puzzles 10D and 10E or removing the laces from the poles. In the following description, description of the same configuration as that of the wisdom ring puzzle 10 of the first embodiment will be omitted. In the following description, in the case of describing the same configuration as the wisdom ring puzzle 10, the description may be omitted by adding the letters "D" or "E" after the symbols shown in FIG. 1A.

[3-1. Structure of Wisdom Ring Puzzle 10D]

As shown in FIG. 9A, the wisdom ring puzzle 10D includes a stage 100D, a first structure body 200D, a second structure body 300D, and a third structure body 400D.

The first structure body 200D includes a first ring unit 210D and a first pole 220D. The first ring unit 210D is arranged on the first virtual plane substantially parallel to an upper surface 101D. The first pole 220D is connected to the first ring unit 210D and has an upwardly convex U-shape. In other words, the first pole 220D is connected to the first ring unit 210D, extends in the direction D1 from the connection part with the first ring unit 210D, turns and extends in the direction D2. The first pole 220D extending in the direction D2 reaches the stage 100D crossing over the outer side (direction D3 side) of the first ring unit 210D. In a plan view, the first pole 220D is connected to the first ring unit 210D at an end portion of the first ring unit 210D in the direction D4. The first pole 220D extends in the direction D3 from the connection part with the first ring unit 210D, crosses the first ring unit 210D, and reaches the stage 100D.

The second structure body 300D includes a second ring unit 310D and the second pole 320D. The second ring unit 310D is arranged on a second virtual plane substantially orthogonal to the upper surface 101D. The second pole 320D is connected to the second ring unit 310D and has an upwardly convex U-shape. In other words, the second pole 320D is connected to the second ring unit 310D, extends in the direction D1 from the connection part with the second ring unit 310D, turns and extends in the direction D2, and reaches the stage 100D.

The third structure body 400D includes a third pole 420D. The third pole 420D has an upwardly convex U-shaped shape. In other words, the third pole 420D is connected to the stage 100D, extends in the direction D1 from the stage 100D, turns and extends in the direction D2. A gap is arranged between a tip 430D of the third pole 420D extending in the direction D2 and the stage 100D.

The first ring unit 210D is positioned in the direction D1 with respect to the stage 100D. The second ring unit 310D is positioned in the direction D1 with respect to the first ring unit 210D. As described above, in the present embodiment, the first virtual plane on which the first ring unit 210D is arranged is substantially parallel to the upper surface 101D, and the second virtual plane on which the second ring unit 310D is arranged is substantially orthogonal to the upper surface 101D. However, the present invention is not limited to the above configuration. For example, the angle formed by the upper surface 101D and the first virtual plane may be smaller than the angle formed by the upper surface 101D and the second virtual plane.

The first pole 220D extends in the direction D1 from the connection part with the first ring unit 210D and crosses over the outer side (direction D3 side) of the first ring unit 210D in the direction D2 after passing through the inner side of the second ring unit 310D. Since the second ring unit 310D is positioned in the direction D1 with respect to the first ring unit 210D, the first pole 220D passes through the inner side of the second ring unit 310D at the side of the direction D1 of the first ring unit 210D. In a plan view, the first pole 220D extends from the connection part with the first ring unit 210D toward (direction D3) the position where the second pole 320D is connected to the stage 100D, passes through the inner side of the second ring unit 310D, and is connected to the stage 100D at a position crossing over the tip 430D. In a plan view, the second pole 320D extends in the direction D3 from the second ring unit 310D and is connected to the

stage 100D at a position crossing over the position where the first pole 220D is connected to the stage 100D.

The first ring unit 210D is connected to the first pole 220D at the side of the direction D4 of the first pole 220D. The second ring unit 310D is arranged in the direction D4 with respect to the second pole 320D. The tip 430D is arranged in the direction D3 with respect to a position where the third pole 420D is connected to the stage 100D. That is, although the first pole 220D and the second pole 320D are folded back in the same direction (direction D4), the third pole 420D turns in the direction opposite to the first pole 220D and the second pole 320D (direction D3). The third pole 420D extends in the direction D1 from the stage 100D and passes through the inner side of the first ring unit 210D in the direction D1.

In other words, in a plan view, the position where the first pole 220D is connected to the stage 100D is positioned between the position where the second pole 320D is connected to the stage 100D and the second ring unit 310D. The second ring unit 310D is positioned between the position where the first ring unit 210D is connected to the first pole 220D and the position where the first pole 220D is connected to the stage 100D.

[3-2. Structure of Wisdom Ring Puzzle 10E]

As shown in FIG. 9B, a wisdom ring puzzle 10E includes a stage 100E, a first structure body 200E, a second structure body 300E, and a third structure body 400E. The wisdom ring puzzle 10E shown in FIG. 9B is similar to the wisdom ring puzzle 10D shown in FIG. 9A, but the directions of the first structure body 200E and the third structure body 400E are different from the first structure body 200D and the third structure body 400D of the wisdom ring puzzle 10D. In the following description, the difference between the wisdom ring puzzle 10D and the wisdom ring puzzle 10E will be mainly explained. In the following description, in the case of describing the same configuration as the wisdom ring puzzle 10D, the description may be omitted by adding the letter "E" instead of the letter "D" after the symbols shown in FIG. 9A.

As shown in FIG. 9B, in the wisdom ring puzzle 10E, the directions of the first structure body 200E and the third structure body 400E are opposite to the directions of the first structure body 200D and the third structure body 400D in FIG. 9A. That is, the first ring unit 210E is arranged in the direction D3 with respect to a position where the first pole 220E is connected to the stage 100E. A tip 430E is arranged in the direction D4 with respect to a position where a third pole 420E is connected to the stage 100E. That is, the second pole 320E and the third pole 420E are folded back toward the same direction (direction D3) after extending in the direction D1 from the stage 100E, but the first pole 220E turns toward the opposite direction (direction D4) from the second pole 320E and the third pole 420E after extending in the direction D1 from the stage 100E.

The above configuration will be described in detail. In a plan view, the first pole 220E extends in the direction D4 from a connection part with the first ring unit 210E, passes through the inner side of a second ring unit 310E, and is connected to the stage 100E at a position crossing over the tip 430E. In a plan view, the second pole 320E extends in the direction D3 from the second ring unit 310E and is connected to the stage 100E at a position crossing over the first ring unit 210E.

In other words, in a plan view, the position where the first ring unit 210E is connected to the first pole 220E is positioned between the position where the second pole 320E is connected to the stage 100E and the second ring unit 310E. The second ring unit 310E is positioned between a

21

position where the first ring unit **210E** is connected to the first pole **220E** and a position where the first pole **220E** is connected to the stage **100E**.

In FIG. 9A and FIG. 9B, although a configuration in which the first poles **220D** and **220E** pass through the inner side of the second ring units **310D** and **310E** in the vicinity of the uppermost portion of the first poles **220D** and **220E** is shown, it is not limited to this configuration. It is sufficient that the first poles **220D** and **220E** pass through the inner side of the second ring units **310D** and **310E** between the connection part between the first ring units **210D** and **210E** and the position where the first poles **100D** and **100E** connect to the first pole **220D**. Therefore, for example, the second virtual plane on which the second ring units **310D** and **310E** are arranged may be parallel to the upper surface **101D** of the stage **100D**. Similarly, it is sufficient that the third poles **420D** and **420E** pass through the inner side of the first ring units **210D** and **210E**, and the first virtual plane arranged with the first ring units **210D** and **210E** may not be parallel to the upper surface **101D**.

[3-3. Method of Solving Wisdom Ring Puzzle 10D]

A method **1000D** of solving the wisdom ring puzzle **10D** shown in FIG. 9A will be described with reference to FIG. 10. The wisdom ring puzzle **10D** is a puzzle targeting a state in which the lace **20D** is entangled only with the second pole **320D** (a state in which only the second pole **320D** exists at the inner side of the lace **20D**).

First, the lace **20D** is arranged so that the first structure body **200D** to the third structure body **400D** are all positioned on the inner side of the lace **20D**. That is, in a state where the lace **20D** is placed on the stage **100D**, the first pole **220D** to the third pole **420D** are sandwiched (surrounded) by the lace **20D**. From that state, as shown in (A) of FIG. 10, the tip **21D** of the lace **20D** passes through the inner side of the first ring unit **210D** in the direction **D1** (1).

As shown in (B) of FIG. 10, the tip **21D** of the lace **20D** moves in the direction **D2** toward the tip **430D** between the third pole **420D** and the first pole **220D**, crosses over the tip **430D** in the direction **D4** (2), and moves in the direction **D4** with respect to the third pole **420D** in the direction **D1** (2). Thereafter, the tip **21D** passes through the inner side of the first ring unit **210D** in the direction **D2** (3). According to this operation, a state in which only the first pole **220D** and the second pole **320D** exist on the inner side of the lace **20D** can be obtained.

As shown in (C) of FIG. 10, the tip **21D** of the lace **20D** moves between the third pole **420D** and the first pole **220D** in the direction **D1** (4) and passes through the inner side of the second ring unit **310D** in the direction **D4** (5). That is, the lace **20D** hangs on the inner side of the second ring unit **310D** and hangs down in the direction **D2**.

As shown in (D) of FIG. 10, the tip **21D** of the lace **20D** crosses over the uppermost portion of the third pole **420D** in the direction **D3** (6), moves in the direction **D2** toward the tip **430D** between the third pole **420D** and the first pole **220D** (7), and crosses over the tip **430D** in the direction **D4**. In this state, the lace **20D** sandwiches the first ring unit **210D** from the outer side of the first ring unit **210D**.

As shown in (E) of FIG. 10, the tip **21D** of the lace **20D** passes through the inner side of the first ring unit **210D** in the direction **D1** (8). That is, the lace **20D** enters the inner side of the first ring unit **210D** from the outer side of the first ring unit **210D**.

As shown in (F) of FIG. 10, the tip **21D** of the lace **20D** crosses over the outer side (direction **D3** side) of the first ring unit **210D** in the direction **D2** (9), moves in the direction **D2** along the third pole **420D**, crosses over the tip **430D** in

22

the direction **D3**, moves in the direction **D1** between the third pole **420D** and the first pole **220D** (10), and moves in the direction **D1** along the third pole **21D**.

As shown in (G) of FIG. 10, the tip **21D** of the lace **20D** crosses over the uppermost portion of the third pole **420D** in the direction **D4** and passes through the inner side of the first ring unit **210D** in the direction **D2** (11). In this state, the lace **20D** in the vicinity of the tip **21D** is positioned at the outer side of the first ring unit **210D**. This is the difference between the state shown in (C) of FIG. 10 and the state shown in (G) of FIG. 10.

As shown in (H) of FIG. 10, the tip **21D** of the lace **20D** crosses over the outer side (direction **D4** side) of the first ring unit **210D** in the direction **D1** (12), moves in the direction **D1** along the first pole **220D** (12), and passes through the inner side of the second ring unit **310D** in the direction **D3** (13). Thereafter, as the tip **21D** moves along the first pole **220D** in the direction **D2**, the lace **20D** is in a state of being entangled only with the second pole **320D** (a state in which the puzzle is solved). In this state, only the second pole **320D** exists at the inner side of the lace **20D**.

[3-4. Method of Solving Wisdom Ring Puzzle 10E]

A method **1000E** of solving the wisdom ring puzzle **10E** shown in FIG. 9B will be described with reference to FIG. 11. The wisdom ring puzzle **10E** is a puzzle targeting a state in which a lace **20E** is entangled only with the second pole **320E** (a state in which only the second pole **320E** exists at the inner side of the lace **20E**).

As shown in (A) of FIG. 11, a tip **21E** of the lace **20E** passes through the inner side of the second ring unit **310E** in the direction **D3** (1) and moves in the direction **D2** along the first pole **220E** (2). In this state, the lace **20E** in the vicinity of the tip **21E** is positioned at the outer side of the first ring unit **210E**.

As shown in (B) of FIG. 11, the tip **21E** of the lace **20E** passes through the inner side of the first ring unit **210E** in the direction **D1** (3). That is, the lace **20E** enters the inner side of the first ring unit **210E** from the outer side of the first ring unit **210E**.

As shown in (C) of FIG. 11, the tip **21E** of the lace **20E** crosses over the uppermost portion of the third pole **420E** in an area in the direction **D2** with respect to the second ring unit **310E** (4), moves in the direction **D2** between the third pole **420E** and the first pole **220E**, and crosses over the tip **430E** in the direction **D2**.

As shown in (D) of FIG. 11, the tip **21E** of the lace **20E** crosses over the side of the direction **D1** of the first ring unit **210E** from the outer side of the first ring unit **210E** and passes through the inner side of the first ring unit **210E** in the direction **D2** (6).

As shown in (E) of FIG. 11, the tip **21E** of the lace **20E** crosses over the tip **430E** in the direction **D4** and moves in the direction **D1** between the third pole **420E** and the first pole **220E** (7).

As shown in (F) of FIG. 11, the tip **21E** of the lace **20E** crosses over the uppermost portion of the third pole **420E** in the direction **D3** in an area in the direction **D2** with respect to the second ring unit **310E** (8), passes through the inner side of the second ring unit **310E** in the direction **D4** (9), moves between the third pole **420E** and the first pole **220E** in the direction **D2** (10), and crosses over the tip **430E** in the direction **D2**. In this state, the lace **20E** is in a state of being entangled only with the first pole **220E**. In this state, only the first pole **220E** exists at the inner side of the lace **20E**.

As shown in (G) of FIG. 11, the tip **21E** of the lace **20E** passes through the inner side of the first ring unit **210E** in the direction **D1**, crosses over the side of the direction **D1** of the

first ring unit **210E** in the direction D4, and moves in the direction D4 with respect to the first ring unit **210E** in the direction D2 (11). That is, the lace **20E** is hung on the first ring unit **210E** such that the tip **21E** is directed from the inner side to the outer side of the first ring unit **210E**.

As shown in (H) of FIG. 11, the tip **21E** of the lace **20E** crosses over the tip **430E** in the direction D4, moves in the direction D1 between the third pole **420E** and the first pole **220E** (12), crosses over the uppermost portion of the third pole **420E** in the direction D3 in an area in the direction D2 with respect to the second ring unit **310E**, and passes through the inner side of the first ring unit **210E** in the direction D2 (13). In this state, the lace **20E** is entangled with the first pole **220E** and the third pole **420E**. In this state, only the first pole **220E** and the third pole **420E** exist on the inner side of the lace **20E**.

From the state shown in (H) of FIG. 11, while the position of the tip **21E** of the lace **20E** is maintained between the second pole **320E** and the third pole **420E**, the other end (not shown) of the lace **20E** moves in the direction D1 along the first pole **220E** and the second pole **320E**, crosses over the uppermost portion of the second pole **320E** in the direction D3, and moves in the direction D2 along the second pole **320E** (14). According to this operation, the lace **20E** is in a state of being entangled only with the second pole **320E** (a state in which the puzzle is solved). In this state, only the second pole **320E** exists at the inner side of the lace **20E**.

4. Fourth Embodiment

A wisdom ring puzzle **10F** according to the fourth embodiment will be described with reference to FIG. 12 to FIG. 16. FIG. 12 is a diagram illustrating a structure of a wisdom ring puzzle according to an embodiment of the present invention. FIG. 13 to FIG. 16 are diagrams showing a method of solving a wisdom ring puzzle according to an embodiment of the present invention. As in the first to third embodiments, the wisdom ring puzzle **10F** is a puzzle using a lace **20F**. The player enjoys the wisdom ring puzzle **10F** by entangling the lace **20F** with a pole (for example, a second pole **320F**) arranged on the wisdom ring puzzle **10F** or removing the lace **20F** from the pole. In the following description, description of the same configuration as that of the wisdom ring puzzle **10** of the first embodiment will be omitted. In the following description, in the case of describing the same configuration as the wisdom ring puzzle **10**, the description may be omitted by adding the letter "F" after the symbols shown in FIG. 1A.

[4-1. Structure Wisdom Ring Puzzle **10F**]

As shown in FIG. 12, the wisdom ring puzzle **10F** includes a stage **100F**, a first structure body **200F**, a second structure body **300F**, a third structure body **500F**, and a fourth structure body **600F**.

The first structure body **200F** includes a first ring unit **210F** and a first pole **220F**. The first ring unit **210F** is arranged on a first virtual plane substantially parallel to an upper surface **101F**. The first pole **220F** is connected to the first ring unit **210F** and has an upwardly convex U-shaped shape. In other words, the first pole **220F** is connected to the first ring unit **210F**, extends in the direction D1 from a connection part with the first ring unit **210F**, turns and extends in the direction D2. The first pole **220F** extending in the direction D2 passes through the inner side of the first ring unit **210F** and reaches the stage **100F**. In a plan view, the first pole **220F** is connected to the first ring unit **210F** at an end portion of the first ring unit **210F** in the direction D3. In a plan view, the first pole **220F** extends in the direction D4

from the connection part with the first ring unit **210F** and reaches the stage **100F** at the inner side of the first ring unit **210F**.

The second structure body **300F** includes a second ring unit **310F** and a second pole **320F**. The second ring unit **310F** is arranged on a second virtual plane substantially orthogonal to the upper surface **101F**. The second pole **320F** extends from an end portion of the second ring unit **310F** in the direction D2 toward the stage **100F** and is connected to the stage **100F**. However, a position where the second pole **320F** is connected to the second ring unit **310F** is not limited to the above-described configuration.

The third structure body **500F** includes a third ring unit **510F** and a third pole **520F**. The third ring unit **510F** is arranged on a third virtual plane substantially parallel to the upper surface **101F**. The third pole **520F** is connected to the third ring unit **510F** and has an upwardly convex U-shaped shape. In other words, the third pole **520F** is connected to the third ring unit **510F**, extends in the direction D1 from a connection part with the third ring unit **510F**, turns and extends in the direction D2. The third pole **520F** extending in the direction D2 passes through the inner side of the third ring unit **510F** and reaches the stage **100F**. In a plan view, the third pole **520F** is connected to the third ring unit **510F** at an end portion of the third ring unit **510F** in the direction D4. In a plan view, the third pole **520F** extends in the direction D3 from a connection part with the third ring unit **510F** and reaches the stage **100F** at the inner side of the third ring unit **510F**. Although details will be described later, in the present embodiment, the first pole **220F** and the third pole **520F** are partially common. Therefore, in the following description, a part of the third pole **520F** that is in common with the first pole **220F** may be referred to as the first pole **220F**. However, the first pole **220F** and the third pole **520F** may be independent. Further, a position where the third pole **520F** is connected to the third ring unit **510F** is not limited to the above-described configuration.

The fourth structure body **600F** includes a fourth ring unit **610F** and a fourth pole **620F**. The fourth ring unit **610F** is arranged on a fourth virtual plane substantially orthogonal to the upper surface **101F**. The fourth pole **620F** extends from an end portion of the fourth ring unit **610F** in the direction D2 toward the stage **100F** and is connected to the stage **100F**. However, a position where the fourth pole **620F** is connected to the fourth ring unit **610F** is not limited to the above-described configuration.

The first ring unit **210F** is positioned in the direction D1 with respect to the stage **100F**. The second ring unit **310F** is positioned in the direction D1 with respect to the first ring unit **210F**. The third ring unit **510F** is positioned in the direction D1 with respect to the first ring unit **210F**. The fourth ring unit **610F** is positioned in the direction D1 with respect to the third ring unit **510F**. As described above, in the present embodiment, the first virtual plane on which the first ring unit **210F** is arranged and the third virtual plane on which the third ring unit **510F** is arranged are substantially parallel to the upper surface **101F**. The second virtual plane on which the second ring unit **310F** is arranged and the fourth virtual plane on which the fourth ring unit **610F** is arranged are substantially orthogonal to the upper surface **101F**. However, the present invention is not limited to the above configuration. For example, the angle formed by the upper surface **101F** and the first virtual plane and the angle formed by the upper surface **101F** and the third virtual plane may be smaller than the angle formed by the upper surface **101F** and the second virtual plane and the angle formed by the upper surface **101F** and the fourth virtual plane.

In the present embodiment, although the configuration in which all of the fourth ring units **610F** are positioned in the direction D1 with respect to the third ring unit **510F** is exemplified, the configuration is not limited to this configuration. For example, a part of the fourth ring unit **610F** may be positioned in the direction D1 with respect to the third ring unit **510F**. That is, when viewed from the side, the third ring unit **510F** and the fourth ring unit **610F** may intersect.

The first pole **220F** extends in the direction D1 from the connection part with the first ring unit **210F**, passes through the inner side of the second ring unit **310F**, and then passes through the inner side of the first ring unit **210F** in the direction D2. In the present embodiment, although the first pole **220F** passes through the inner side of the second ring unit **310F** in the vicinity of the uppermost portion of the first pole **220F**, it is not limited to this configuration. For example, it is sufficient that the first pole **220F** passes through the inner side of the second ring unit **310F** between the connection part with the first ring unit **210F** and the position passing through the inner side of the first ring unit **210F** in the direction D2. In a plan view, the first pole **220F** extends from the connection part with the first ring unit **210F** toward the fourth pole **620F** (direction D4), passes through the inner side of the second ring unit **310F**, and is connected to the stage **100F** in an area where the first ring unit **210F** and the third ring unit **510F** overlap.

The second pole **320F** extends in the direction D2 from the end portion of the second ring unit **310F** in the direction D2. The second pole **320F** passes through the inner side of the first ring unit **210F** in the direction D2 and is connected to the stage **100F**.

The third pole **520F** extends in the direction D1 from the connection part with the third ring unit **510F**, passes through the inner side of the fourth ring unit **610F**, and then passes through the inner side of the third ring unit **510F** in the direction D2. In the present embodiment, although the third pole **520F** passes through the inner side of the fourth ring unit **610F** in the vicinity of the uppermost portion of the third pole **520F**, it is not limited to this configuration. For example, it is sufficient that the third pole **520F** passes through the inner side of the fourth ring unit **610F** between the connection part with the third ring unit **510F** and the position passing through the inner side of the third ring unit **510F** in the direction D2. In a plan view, the third pole **520F** extends from the connection part with the third ring unit **510F** toward the second pole **320F** (direction D3), passes through the inner side of the fourth ring unit **610F**, and is connected to the stage **100F** in an area where the first ring unit **210F** and the third ring unit **510F** overlap.

The fourth pole **620F** extends in the direction D2 from the end portion of the fourth ring unit **610F** in the direction D2. The fourth pole **620F** passes through the inner side of the third ring unit **510F** in the direction D2 and is connected to the stage **100F**.

[4-2. Method of Solving Wisdom Ring Puzzle **10F** (Part 1)]

A method **1000F** of solving the wisdom ring puzzle **10F** shown in FIG. 12 will be described with reference to FIG. 13 and FIG. 14. The wisdom ring puzzle **10F** is a puzzle targeting a state in which the lace **20F** is entangled only with the second pole **320F** (a state in which only the second pole **320F** exists at the inner side of the lace **20F**).

In the method of solving the wisdom ring puzzle **10F**, since the method up to the state of (A) of FIG. 13 is the same as that of (A) of FIG. 2 to (D) of FIG. 2, description thereof will be omitted. Also, the first structure body **200** in FIG. 2 corresponds to the fourth structure body **500F** in FIG. 12, the second structure body **300** in FIG. 2 corresponds to the

fourth structure body **600F** in FIG. 12, and the third structure body **400** in FIG. 2 corresponds to the first structure body **200F** and the second structure body **300F** in FIG. 12. The state of (A) of FIG. 13 is a state in which the lace **20F** is entangled with the first pole **220F** (the third pole **520F**) and the second pole **320F**.

As shown in (B) of FIG. 13, the tip **21F** of the lace **20F** passes through the inner side of the first ring unit **210F** in the direction D1 (1), moves in the direction D1 along the third pole **520F**, passes through the inner side of the fourth ring unit **610F** in the direction D4 (2), and passes through the inner side of the third ring unit **510F** in the direction D2 (3). That is, the lace **20F** hangs on the inner side of the fourth ring unit **610F** and hangs down in the direction D2 so as to pass through the inner side of the third ring unit **510F**.

As shown in (C) of FIG. 13, the tip **21F** of the lace **20F** crosses over the outer side (direction D2 side) of the third ring unit **510F** while maintaining a state in which the lace **20F** sandwiches the third ring unit **510F** (4), moves in the direction D1 along the third pole **520F**, crosses over the fourth ring unit **610F** in the direction D3 (5), moves in the direction D2 along the third pole **520F** (6), and crosses over the outer side (direction D3 side) of the third ring unit **510F** (7). In this case, the tip **21F** of the lace **20F** is in a state where it can be caught at a branch point between the third pole **520F** and the first pole **220F**.

As shown in (D) of FIG. 13, the tip **21F** of the lace **20F** passes through the inner side of the third ring unit **510F** in the direction D1 (8), crosses over the fourth ring unit **610F** in the direction D4 (9), and moves in the direction D2 along the third pole **520F**. In this state, the lace **20F** in the vicinity of the tip **21F** is positioned at the outer side of the third ring unit **510F**.

As shown in (E) of FIG. 13, the tip **21F** of the lace **20F** moves in the direction D1 along the third pole **520F**, passes through the inner side of the fourth ring unit **610F** in the direction D3 (10), moves in the direction D2 along the third pole **520F** (11), and passes through the inner side of the third ring unit **510F** in the direction D2 (12). In this case, the tip **21F** of the lace **20F** is in a state where it can be caught at the branch point between the third pole **520F** and the first pole **220F**. In this state, the lace **20F** sandwiches the first pole **220F** and the second pole **320F**.

As shown in (F) of FIG. 13, the tip **21F** of the lace **20F** passes through the inner side of the second ring unit **310F** in the direction D3 (13). In this state, the lace **20F** sandwiches the first pole **220F** and the first pole **220F**.

As shown in (G) of FIG. 13, the tip **21F** of the lace **20F** crosses over the second ring unit **310F** in the direction D4 (14), passes through the inner side of the third ring unit **510F** in the direction D1 (15), moves in the direction D1 along the third pole **520F**, and passes through the inner side of the fourth ring unit **610F** in the direction D4. In this state, the lace **20F** in the vicinity of the tip **21F** is positioned at the outer side of the third ring unit **510F**.

As shown in (H) of FIG. 13, the tip **21F** of the lace **20F** crosses over the fourth ring unit **610F** in the direction D3 (17). Thereafter, the tip **21F** moves in the direction D2 along the third pole **520F**, passes through the inner side of the third ring unit **510F** in the direction D2 (18), turns and crosses over the outer side (direction D3 side) of the third ring unit **510F** in the direction D1 (18). Then, the tip **21F** crosses over the fourth ring unit **610F** in the direction D4 (18). In this state, the lace **20F** hangs on the inner side of the fourth ring unit **610F** and hangs down in the direction D2 so as to pass through the inner side of the third ring unit **510F**.

As shown in (A) of FIG. 14, the tip 21F of the lace 20F passes through the inner side of the third ring unit 510F in the direction D1, passes through the inner side of the fourth ring unit 610F in the direction D3, and passes through the inner side of the third ring unit 510F in the direction D2 (20). Thereafter, the tip 21F moves in the direction D2 along the third pole 520F and passes through the inner side of the first ring unit 210F in the direction D2 (21).

As shown in (B) of FIG. 14, the tip 21F of the lace 20F crosses over the outer side (direction D4 side) of the first ring unit 210F in the direction D1 (22), moves in the direction D1 along the third pole 520F and the fourth pole 620F, passes through the inner side of the third ring unit 510F in the direction D1 (23), passes through the inner side of the fourth ring unit 610F in the direction D4 (24), moves in the direction D2 along the fourth pole 620F, and passes through the inner side of the third ring unit 510F in the direction D2 (25). In this state, the lace 20F hangs on the inner side of the fourth ring unit 610F and hangs down in the direction D2 so as to pass through the inner side of the third ring unit 510F.

As shown in (C) of FIG. 14, the tip 21F of the lace 20F crosses over the outer side (direction D4 side) of the third ring unit 510F in the direction D1 (26), moves in the direction D1 along the third pole 520F, crosses over the fourth ring unit 610F in the direction D3 (27), moves in the direction D2 along the third pole 520F, and crosses over the outer side (direction D3 side) of the third ring unit 510F in the direction D2 (28).

As shown in (D) of FIG. 14, the tip 21F of the lace 20F passes through the inner side of the third ring unit 510F in the direction D1 (29) and crosses over the fourth ring unit 610F in the direction D4 (30).

As shown in (E) of FIG. 14, the tip 21F of the lace 20F moves in the direction D1 along the third pole 520F, passes through the inner side of the fourth ring unit 610F in the direction D3 (31), moves in the direction D2 along the third pole 520F, and passes through the inner side of the third ring unit 510F in the direction D2 (32).

As shown in (F) of FIG. 14, the tip 21F of the lace 20F crosses over the second ring unit 310F in the direction D3 (33). When the lace 20F extending from the tip 21F is pulled in this state (34), the lace 20F is in a state of being entangled only with the second pole 320F (a state in which the puzzle is solved). In this state, only the second pole 320F exists at the inner side of the lace 20F.

[4-3. Method of Solving Wisdom Ring Puzzle 10F (Part 2)]

Another method 1000F of solving the wisdom ring puzzle 10F shown in FIG. 12 will be described with reference to FIG. 15 and FIG. 16. Unlike the method (Part 1) shown in FIG. 13 and FIG. 14, the method (Part 2) shown in FIG. 15 and FIG. 16 starts with the lace 20F not being entangled with any of the poles.

As shown in (A) of FIG. 15, the tip 21F of the lace 20F passes through the inner side of the first ring unit 210F in the direction D1 between the second pole 320F and the first pole 220F (third pole 520F) (1). Thereafter, the tip 21F moves in the direction D1 along the second pole 320F, passes through the inner side of the second ring unit 310F in the direction D3 (2), moves in the direction D2 along the second pole 320F, and passes through the inner side of the first ring unit 210F in the direction D2.

As shown in (B) of FIG. 15, the tip 21F of the lace 20F crosses over the outer side (direction D3 side) of the first ring unit 210F in the direction D1 (4), crosses over the second ring unit 310F in the direction D4 (5), passes through the inner side of the third ring unit 510F in the direction D1

(6), and passes through the inner side of the fourth ring unit 610F in the direction D4 (7). In this state, the lace 20F in the vicinity of the tip 21F is positioned at the outer side of the third ring unit 510F.

As shown in (C) of FIG. 15, the tip 21F of the lace 20F crosses over the fourth ring unit 610F in the direction D3 (8), moves in the direction D2 along the third pole 520F, passes through the inner side of the third ring unit 510F in the direction D2 (9), turns and crosses over the outer side (direction D3 side) of the third ring unit 510F in the direction D1 (9). Thereafter, the tip 21F moves in the direction D1 along the third pole 520F (10), and crosses over the fourth ring unit 610F in the direction D4 (11). In this state, the lace 20F hangs on the inner side of the fourth ring unit 610F and hangs down in the direction D2 so as to pass through the inner side of the third ring unit 510F.

As shown in (D) of FIG. 15, the tip 21F of the lace 20F passes through the inner side of the third ring unit 510F in the direction D1 (12), passes through the inner side of the fourth ring unit 610F in the direction D3 (13), passes through the inner side of the third ring unit 510F in the direction D2 (14), and crosses over the outer side (direction D4 side) of the first ring unit 210F in the direction D2.

As shown in (E) of FIG. 15, the tip 21F of the lace 20F passes through the inner side of the first ring unit 210F in the direction D1 (16), moves in the direction D1 along the third pole 520F, passes through the inner side of the third ring unit 510F in the direction D1 (17), passes through the inner side of the fourth ring unit 610F in the direction D4 (18), and passes through the inner side of the third ring unit 510F in the direction D2 (19). In this state, the lace 20F hangs on the inner side of the fourth ring unit 610F and hangs down in the direction D2 so as to pass through the inner side of the third ring unit 510F.

As shown in (F) of FIG. 15, the tip 21F of the lace 20F crosses over the outer side (direction D4 side) of the third ring unit 510F in the direction D1 (20), moves in the direction D1 along the third pole 520F, and crosses over the fourth ring unit 610F in the direction D3 (21). Thereafter, the tip 21F crosses over the outer side (direction D3 side) of the third ring unit 510F in the direction D2, turns, passes through the inner side of the third ring unit 510F in the direction D1 (22), moves in the direction D1 along the third pole 520F, and crosses over the fourth ring unit 610F in the direction D4 (23). In this state, the lace 20F in the vicinity of the tip 21F is positioned at the outer side of the third ring unit 510F. This is the difference between the state shown in (E) of FIG. 15 and the state shown in (F) of FIG. 15.

As shown in (G) of FIG. 15, the tip 21F of the lace 20F passes through the inner side of the fourth ring unit 610F in the direction D3 (24), moves in the direction D2 along the third pole 520F, passes through the inner side of the third ring unit 510F in the direction D2 (25), crosses over the second ring unit 310F in the direction D3 (26), moves in the direction D2 along the first pole 220F, and crosses over the outer side (direction D3 side) of the first ring unit 210F in the direction D2.

As shown in (H) of FIG. 15, the tip 21F of the lace 20F passes through the inner side of the second ring unit 310F in the direction D4 (27). In this state, the lace 20F passes through the inner side of the first ring unit 210F and turns so as to sandwich the first pole 220F at the side of the direction D1 of the first ring unit 210F.

As shown in (A) of FIG. 16, the tip 21F of the lace 20F passes through the inner side of the third ring unit 510F in the direction D1 (28), moves in the direction D1 along the third pole 520F, and passes through the inner side of the

fourth ring unit **610F** in the direction D4 (29). In this state, the lace **20F** in the vicinity of the tip **21F** is positioned at the outer side of the third ring unit **510F**.

As shown in (B) of FIG. 16, the tip **21F** of the lace **20F** crosses over the fourth ring unit **610F** in the direction D3 (30). Thereafter, the tip **21F** moves in the direction D2 along the third pole **520F**, passes through the inner side of the third ring unit **510F** in the direction D2, turns and crosses over the outer side (direction D3 side) of the third ring unit **510F** in the direction D1 (31). Then, the tip **21F** crosses over the fourth ring unit **610F** in the direction D3 (32). In this state, the lace **20F** hangs on the inner side of the fourth ring unit **610F** and hangs down in the direction D2 so as to pass through the inner side of the third ring unit **510F**.

As shown in (C) of FIG. 16, the tip **21F** of the lace **20F** passes through the inner side of the third ring unit **510F** in the direction D1 (33), passes through the inner side of the fourth ring unit **610F** in the direction D3 (34), moves in the direction D2 along the third pole **520F**, passes through the inner side of the third ring unit **510F** in the direction D2 (35), and further passes through the inner side of the first ring unit **210F** in the direction D2 (36). In this state, the lace **20F** is entangled only with the first pole **220F** (or the first pole **220F** and the third pole **520F**).

As shown in (D) of FIG. 16, the tip **21F** of the lace **20F** crosses over the outer side (direction D4 side) of the first ring unit **210F** in the direction D1 (37), moves in the direction D1 along the third ring unit **520F**, passes through the inner side of the third ring unit **510F** in the direction D1 (38), further moves in the direction D1 along the third ring unit **520F**, passes through the inner side of the fourth ring unit **610F** in the direction D4 (39), and passes through the inner side of the third ring unit **510F** in the direction D2 (40).

As shown in (E) of FIG. 16, the tip **21F** of the lace **20F** crosses over the outer side (direction D4 side) of the third ring unit **510F** in the direction D1 (41), moves in the direction D1 along the third pole **520F**, crosses over the fourth ring unit **610F** in the direction D3 (42), moves in the direction D2 along the third pole **520F**, and crosses over the outer side (direction D3 side) of the third ring unit **510F** in the direction D2 (43).

As shown in (F) of FIG. 16, the tip **21F** of the lace **20F** turns after crossing over the outer side of the third ring unit **510F** in the direction D2, passes through the inner side of the third ring unit **510F** in the direction D1 (44), further moves in the direction D1 along the third pole **520F**, and crosses over the fourth ring unit **610F** in the direction D4 (45). In this state, the lace **20F** in the vicinity of the tip **21F** is positioned at the outer side of the third ring unit **510F**.

As shown in (G) of FIG. 16, the tip **21F** of the lace **20F** passes through the inner side of the fourth ring unit **610F** in the direction D3 (46), moves in the direction D2 along the third pole **520F**, and passes through the inner side of the third ring unit **510F** in the direction D2 (47). Then, as shown in (H) of FIG. 16, the tip **21F** crosses over the second ring unit **310F** in the direction D3, so that the lace **20F** is in a state of being entangled only with the second pole **320F** (a state in which the puzzle is solved). In this state, only the second pole **320F** exists at the inner side of the lace **20F**.

5. Fifth Embodiment

A wisdom ring puzzle **10G** according to a fifth embodiment will be described with reference to FIG. 17 to FIG. 21. FIG. 17 is a diagram illustrating a structure of a wisdom ring puzzle according to an embodiment of the present invention. FIG. 18 to FIG. 21 are diagrams showing a method of

solving a wisdom ring puzzle according to an embodiment of the present invention. As in the first to fourth embodiments, the wisdom ring puzzle **10G** is a puzzle using a lace **20G**. The player enjoys the wisdom ring puzzle **20G** by 5 entangling the lace with a pole arranged on the wisdom ring puzzle **10G** (for example, a second pole **320G**) or removing the lace from the pole. In the following description, description of the same configuration as that of the wisdom ring puzzle **10F** of the fourth embodiment will be omitted. In the 10 following description, in the case of describing the same configuration as the wisdom ring puzzle **10F**, the description may be omitted by adding the letter “G” instead of the letter “F” after the symbols shown in FIG. 12.

[5-1. Structure of Wisdom Ring Puzzle **10G**]

A fourth pole **620G** extends in the direction D1 from an 15 end portion of a fourth ring unit **610G** in the direction D1, turns and extends in the direction D2. The fourth pole **620G** extending in the direction D2 passes through the inner side of each of a third ring unit **510G** and a first ring unit **210G** 20 and reaches a stage **100G**. In a plan view, the fourth pole **620G** extends from a connection part with the fourth ring unit **610G** toward the second pole **320G** (D3) and is connected to the stage **100G** at a position crossing over a third pole **520G** and at a position where the third ring unit **510G** 25 and the first ring unit **210G** overlap.

Although the fourth ring unit **610F** is positioned at the uppermost portion in the wisdom ring puzzle **10F** shown in FIG. 12, the fourth pole **620G** is positioned at the uppermost portion in the wisdom ring puzzle **10G** shown in FIG. 17. 30 Further, the wisdom ring puzzle **10G** of FIG. 17 is different from the wisdom ring puzzle **10F** of FIG. 12 in that the fourth pole **620G** (the first pole **220G**) passes through each of the inner sides of the third ring unit **510G** and the first ring unit **210G** in the wisdom ring puzzle **10G** while the third pole **520F** passes through each of the inner sides of the third ring unit **510F** and the first ring unit **210F** in the wisdom ring puzzle **10F**.

[5-2. Method of Solving Wisdom Ring Puzzle **10G** (Part 1)]

A method **1000G** of solving the wisdom ring puzzle **10G** 40 shown in FIG. 17 will be described with reference to FIG. 18 and FIG. 19. The wisdom ring puzzle **10G** is a puzzle targeting a state in which the lace **20G** is entangled only with the second pole **320G** (a state in which only the second pole **320G** exists at the inner side of the lace **20G**).

In the method of solving the wisdom ring puzzle **10G**, 45 since the method up to the state of (A) of FIG. 18 is the same as that of (A) of FIG. 4 to (D) of FIG. 4, description thereof will be omitted. Also, the first structure body **200** in FIG. 4 corresponds to a third structure body **500G** in FIG. 17, the second structure body **300** in FIG. 4 corresponds to a fourth structure **600G** in FIG. 17, and the third structure body **400** in FIG. 4 corresponds to a first structure body **200G** and a second structure body **300G** in FIG. 17. The state of (A) of FIG. 18 is a state in which the lace **20G** is entangled with the first pole **220G** (third pole **520G**) and the second pole **320G**.

As shown in (B) of FIG. 18, the tip **21G** of the lace **20G** passes through the inner side of the first ring unit **210G** in the direction D1 (1), moves in the direction D1 along the third pole **520G**, passes through the inner side of the third ring unit **510G** in the direction D1 (2), and passes through the inner side of the fourth ring unit **610G** in the direction D4 (3). That is, the lace **20G** hangs on the inner side of the fourth ring unit **610G** and hangs down in the direction D2. In this case, the lace **20G** in the vicinity of the tip **21G** is positioned at the outer side of the third ring unit **510G**.

As shown in (C) of FIG. 18, the tip **21G** of the lace **20G** moves in the direction D1 along the third pole **520G** and the

fourth pole 620G, crosses over an uppermost portion of the fourth pole 620G in the direction D3 (4), moves in the direction D2 along the fourth pole 620G (5), and passes through the inner side of the third ring unit 510G in the direction D2 (6).

As shown in (D) of FIG. 18, the tip 21G of the lace 20G crosses over the outer side (direction D3 side) of the third ring unit 510G in the direction D1 (7), moves in the direction D1 along the fourth pole 620G, crosses over the uppermost portion of the fourth pole 620G in the direction D4 (8), moves in the direction D2 along the fourth pole 620G and the third pole 520G, and passes through the inner side of the third ring unit 510G in the direction D2 (9). That is, the lace 20G hangs on the inner side of the fourth ring unit 610G and hangs down in the direction D2 so as to pass through the inner side of the third ring unit 510G.

As shown in (E) of FIG. 18, the tip 21G of the lace 20G passes through the inner side of the fourth ring unit 610G in the direction D3 (10), moves in the direction D2 along the third pole 520G, and passes through the inner side of the third ring unit 510G in the direction D2 (11).

As shown in (F) of FIG. 18, the tip 21G of the lace 20G crosses over the outer side (direction D4 side) of the third ring unit 510G in the direction D1 (12), moves in the direction D1 along the third pole 520G and the fourth pole 620G, and crosses over the uppermost portion of the fourth pole 620G in the direction D3 (13). Thereafter, the tip 21G moves in the direction D2 along the fourth pole 620G (14) and passes through the inner side of the second ring unit 310G in the direction D3 (15). In this state, the lace 20G in the vicinity of the tip 21G is positioned at the outer side of the first ring unit 210G. In addition, the lace 20G sandwiches the first pole 220G and the second pole 320G.

As shown in (G) of FIG. 18, the tip 21G of the lace 20G crosses over the second ring unit 310G in the direction D4 (16), moves in the direction D1 along the fourth pole 620G, and crosses over the uppermost portion of the fourth pole 620G in the direction D4 (17). Thereafter, the tip 21G moves 18 in the direction D2 along the fourth pole 620G and the third pole 520G (18), and crosses over the outer side (direction D4 side) of the third ring unit 510G in the direction D2 (19). In this state, the lace 20G is wound around the second ring unit 310G.

As shown in (H) of FIG. 18, the tip 21G of the lace 20G moves in the direction D1 along the third pole 520G, passes through the inner side of the third ring unit 510G in the direction D1 (20), passes through the inner side of the fourth ring unit 610G in the direction D4 (21), and passes through the inner side of the third ring unit 510G in the direction D2 (22). In this state, the lace 20G hangs on the inner side of the fourth ring unit 610G and hangs down in the direction D2 so as to pass through the inner side of the third ring unit 510G.

As shown in (A) of FIG. 19, the tip 21G of the lace 20G crosses over the outer side (direction D4 side) of the third ring unit 510G in the direction D1 (23), moves in the direction D1 along the third pole 520G and the fourth pole 620G, and crosses over the uppermost portion of the fourth pole 620G in the direction D3 (24). Thereafter, the tip 21G moves in the direction D2 along the fourth pole 620G, crosses over the outer side (direction D3 side) of the third ring unit 510G, turns and passes through the inner side of the third ring unit 510G in the direction D1 (25). Thereafter, the tip 21G moves in the direction D1 along the fourth pole 620G, crosses over the uppermost portion of the fourth pole 620G in the direction D4 (26), moves in the direction D2 along the fourth pole 620G and the third pole 520G, and crosses over the outer side (direction D4 side) of the third

ring unit 510G in the direction D2 (27). In this state, the lace 20G hangs on the inner side of the fourth ring unit 610G, and the lace 20G in the vicinity of the tip 21G is positioned at the outer side of the third ring unit 510G.

5 As shown in (B) of FIG. 19, the tip 21G of the lace 20G crosses over the outer side (direction D4 side) of the third ring unit 510G in the direction D1 (28), passes through the inner side of the fourth ring unit 610G in the direction D3 (29), moves in the direction D2 along the fourth pole 620G, 10 passes through the inner side of the third ring unit 510G in the direction D2 (30), and passes through the inner side of the first ring unit 210G in the direction D2 (31).

As shown in (C) of FIG. 19, the tip 21G of the lace 20G crosses over the outer side (direction D4 side) of the first 15 ring unit 210G in the direction D1 (32), passes through the inner side of the third ring unit 510G in the direction D1 (33), moves in the direction D1 along the third pole 520G, passes through the inner side of the fourth ring unit 610G in the direction D4 (34), moves in the direction D2 along the 20 third pole 520G, and crosses over the outer side (direction D4 side) of the third ring unit 510G in the direction D2 (35).

As shown in (D) of FIG. 19, the tip 21G of the lace 20G crosses over the outer side (direction D4 side) of the third ring unit 510G in the direction D1 (36), moves in the 25 direction D1 along the third pole 520G and the fourth pole 620G, and crosses over the uppermost portion of the fourth pole 620G in the direction D3 (37). Thereafter, the tip 21G moves in the direction D2 along the fourth pole 620G, passes through the inner side of the third ring unit 510G in the direction D2, turns and crosses over the outer side (direction D3 side) of the third ring unit 510G in the direction D1 (38). Thereafter, the tip 21G moves in the direction D1 along the fourth pole 620G, crosses over the uppermost portion of the fourth pole 620G in the direction D4 (39), moves in the direction D2 along the fourth pole 620G and the third pole 520G, and passes through the inner side of the third ring unit 510G in the direction D2 (40). In this state, the lace 20G hangs on the inner side of the fourth ring unit 610G and hangs down in the direction D2 so as to 35 pass through the inner side of the third ring unit 510G.

As shown in (E) of FIG. 19, the tip 21G of the lace 20G passes through the inner side of the third ring unit 510G in the direction D1, passes through the inner side of the fourth ring unit 610G in the direction D3 (41), moves in the 45 direction D2 along the third pole 520G, and passes through the inner side of the third ring unit 510G in the direction D2 (42). In this state, the lace 20G passes through the inner side of the first ring unit 210G in the direction D2 and is entangled with the third pole 520G.

As shown in (F) of FIG. 19, the tip 21G of the lace 20G crosses over the outer side (direction D4 side) of the third ring unit 510G in the direction D1 (43), moves in the direction D1 along the third pole 520G and the fourth pole 620G, and crosses over the uppermost portion of the fourth pole 620G in the direction D3 (44). Thereafter, the tip 21G moves in the direction D2 along the fourth pole 620G, crosses over the second ring unit 310G in the direction D3, and crosses over the outer side (direction D3 side) of the first ring unit 210G in the direction D2 (45). Thereafter, the tip 21G turns and passes through the inner side of the first ring unit 210G in the direction D1 (46), passes through the inner side of the second ring unit 310G in the direction D4 (47), and passes through the inner side of the first ring unit 210G in the direction D2 (48), so that the lace 20G is in a state of 55 being entangled only with the second pole 320G (a state in which the puzzle is solved). In this state, only the second pole 320G exists at the inner side of the lace 20G.

[5-3. Method of Solving Wisdom Ring Puzzle 10G (Part 2)]

Another method 1000G of solving the wisdom ring puzzle 10G shown in FIG. 17 will be described with reference to FIG. 20 and FIG. 21. Unlike the method (Part 1) shown in FIG. 18 and FIG. 19, the method (Part 2) shown in FIG. 20 and FIG. 21 starts with the lace 20G not being entangled with any of the poles.

As shown in (A) of FIG. 20, the tip 21G of the lace 20G passes through the inner side of the first ring unit 210G in the direction D1 between the second pole 320G and the first pole 220G (the fourth pole 620G) (1). Thereafter, the tip 21G moves in the direction D1 along the second pole 320G, passes through the inner side of the second ring unit 310G in the direction D3 (2), moves in the direction D2 along the second pole 320G, and passes through the inner side of the first ring unit 210G in the direction D2.

As shown in (B) of FIG. 20, the tip 21G of the lace 20G crosses over the outer side (direction D3 side) of the first ring unit 210G in the direction D1 (4), crosses over the second ring unit 310G in the direction D4 (5), moves in the direction D1 along the fourth pole 620G (6), and crosses over the uppermost portion of the fourth ring unit 610G in the direction D4 (7). Thereafter, the tip 21G moves in the direction D2 along the fourth pole 620G and the third pole 520G and crosses over the outer side (direction D4 side) of the third ring unit 510G in the direction D2 (8). In this state, the lace 20G is wound around the second ring unit 310G.

As shown in (C) of FIG. 20, the tip 21G of the lace 20G moves in the direction D1 along the third pole 520G, passes through the inner side of the third ring unit 510G in the direction D1 (9), passes through the inner side of the fourth ring unit 610G in the direction D4 (10), and passes through the inner side of the third ring unit 510G in the direction D2 (11). In this state, the lace 20G hangs on the inner side of the fourth ring unit 610G and hangs down in the direction D2 so as to pass through the inner side of the third ring unit 510G.

As shown in (D) of FIG. 20, the tip 21G of the lace 20G crosses over the outer side (direction D4 side) of the third ring unit 510G in the direction D1 (12), moves in the direction D1 along the third pole 520G and the fourth pole 620G, and crosses over the uppermost portion of the fourth pole 620G in the direction D3 (13). Thereafter, the tip 21G moves in the direction D2 along the fourth pole 620G, crosses over the outer side (direction D3 side) of the third ring unit 510G in the direction D2 (14). Thereafter, the tip 21G moves in the direction D1 along the fourth pole 620G, crosses over the uppermost portion of the fourth pole 620G in the direction D4 (15), moves in the direction D2 along the fourth pole 620G and the third pole 520G, moves in the direction D2 along the fourth pole 620G and the third pole 520G, and crosses over the outer side (direction D4 side) of the third ring unit 510G in the direction D2 (16). In this state, the lace 20G hangs on the inner side of the fourth ring unit 610G, and the lace 20G in the vicinity of the tip 21G is positioned at the outer side of the third ring unit 510G.

As shown in (E) of FIG. 20, the tip 21G of the lace 20G crosses over the outer side (direction D4 side) of the third ring unit 510G in the direction D1 (17), passes through the inner side of the fourth ring unit 610G in the direction D3 (18), moves in the direction D2 along the fourth pole 620G, passes through the inner side of the third ring unit 510G in the direction D2 (19), and crosses over the outer side (direction D4 side) of the first ring unit 210G in the direction D2 (20).

As shown in (F) of FIG. 20, the tip 21G of the lace 20G turns after crossing over the outer side of the first ring unit 210G in the direction D2 (21), passes through the inner side of the first ring unit 210G in the direction D1 (21), passes through the inner side of the third ring unit 510G in the direction D1 (22), moves in the direction D1 along the third pole 520G, passes through the inner side of the fourth ring unit 610G in the direction D4 (23), moves in the direction D2 along the third pole 520G, and crosses over the outer side (direction D4 side) of the third ring unit 510G in the direction D2 (24).

As shown in (G) of FIG. 20, the tip 21G of the lace 20G crosses over the outer side (direction D4 side) of the third ring unit 510G in the direction D1 (25), moves in the direction D1 along the third pole 520G and the fourth pole 620G, and crosses over the uppermost portion of the fourth pole 620G in the direction D3 (26). Thereafter, the tip 21G moves in the direction D2 along the fourth pole 620G, passes through the inner side of the third ring unit 510G in the direction D2, turns and crosses over the outer side (direction D3 side) of the third ring unit 510G in the direction D1 (27). Thereafter, the tip 21G moves in the direction D1 along the fourth pole 620G, crosses over the uppermost portion of the fourth pole 620G in the direction D4 (28), moves in the direction D2 along the fourth pole 620G and the third pole 520G, and passes through the inner side of the third ring unit 510G in the direction D2 (29). In this state, the lace 20G hangs on the inner side of the fourth ring unit 610G and hangs down in the direction D2 so as to pass through the inner side of the third ring unit 510G.

As shown in (H) of FIG. 20, the tip 21G of the lace 20G passes through the inner side of the third ring unit 510G in the direction D1, passes through the inner side of the fourth ring unit 610G in the direction D3 (30), moves in the direction D2 along the third pole 520G, and passes through the inner side of the third ring unit 510G in the direction D2 (31). In this state, the lace 20G crosses over the outer side of the first ring unit 210G and is entangled with the third pole 520G.

As shown in (A) of FIG. 21, the tip 21G of the lace 20G crosses over the outer side (direction D4 side) of the third ring unit 510G in the direction D1 (32), moves in the direction D1 along the third pole 520G and the fourth pole 620G, and crosses over the uppermost portion of the fourth pole 620G in the direction D3 (33). Thereafter, the tip 21G moves in the direction D2 along the fourth pole 620G and crosses over the second ring unit 310G in the direction D3 (34). In this state, the lace 20G in the vicinity of the tip 21G is positioned at the outer side of the first ring unit 210G. Further, the lace 20G sandwiches the first pole 220G.

As shown in (B) of FIG. 21, the tip 21G of the lace 20G passes through the inner side of the second ring unit 310G in the direction D4 (35), moves in the direction D1 along the fourth pole 620G, and crosses over the uppermost portion of the fourth pole 620G in the direction D4 (36). Thereafter, the tip 21G moves in the direction D2 along the fourth pole 620G and the third pole 520G and crosses over the outer side (direction D4 side) of the third ring unit 510G in the direction D2 (37).

As shown in (C) of FIG. 21, the tip 21G of the lace 20G moves in the direction D1 along the third pole 520G, passes through the inner side of the third ring unit 510G in the direction D1 (38), passes through the inner side of the fourth ring unit 610G in the direction D4 (39), and passes through the inner side of the third ring unit 510G in the direction D2 (40). In this state, the lace 20G hangs on the inner side of the

fourth ring unit **610G** and hangs down in the direction D2 so as to pass through the inner side of the third ring unit **510G**.

As shown in (D) of FIG. 21, the tip **21G** of the lace **20G** crosses over the outer side (direction D4 side) of the third ring unit **510G** in the direction D1 (41), moves in the direction D1 along the third pole **520G** and the fourth pole **620G**, and crosses over the uppermost portion of the fourth pole **620G** in the direction D3 (42). Thereafter, the tip **21G** moves in the direction D2 along the fourth pole **620G**, crosses over the outer side (direction D3 side) of the third ring unit **510G** in the direction D2, turns and passes through the inner side of the third ring unit **510G** in the direction D1 (43). Thereafter, the tip **21G** moves in the direction D1 along the fourth pole **620G**, crosses over the uppermost portion of the fourth pole **620G** in the direction D4 (44), moves in the direction D2 along the fourth pole **620G** and the third pole **520G**, and crosses over the outer side (direction D4 side) of the third ring unit **510G** in the direction D2 (45). In this state, the lace **20G** hangs on the inner side of the fourth ring unit **610G**, and the lace **20G** in the vicinity of the tip **21G** is positioned at the outer side of the third ring unit **510G**.

As shown in (E) of FIG. 21, the tip **21G** of the lace **20G** crosses over the outer side (direction D4 side) of the third ring unit **510G** in the direction D1 (46), passes through the inner side of the fourth ring unit **610G** in the direction D3 (47), moves in the direction D2 along the fourth pole **620G**, passes through the inner side of the third ring unit **510G** in the direction D2 (48), and passes through the inner side of the first ring unit **210G** in the direction D2 (49). In this state, the lace **20G** is entangled only with the first pole **220G** (the fourth pole **620G**).

As shown in (F) of FIG. 21, the tip **21G** of the lace **20G** crosses over the outer side (direction D4 side) of the first ring unit **210G** in the direction D1 (50), passes through the inner side of the third ring unit **510G** in the direction D1 (51), moves in the direction D1 along the third pole **520G**, passes through the inner side of the fourth ring unit **610G** in the direction D4 (52), moves in the direction D2 along the third pole **520G**, and crosses over the outer side (direction D4 side) of the third ring unit **510G** in the direction D2 (53).

As shown in (G) of FIG. 21, the tip **21G** of the lace **20G** crosses over the outer side (direction D4 side) of the third ring unit **510G** in the direction D1 (54), moves in the direction D1 along the third pole **520G** and the fourth pole **620G**, and crosses over the uppermost portion of the fourth pole **620G** in the direction D3 (55). Thereafter, the tip **21G** moves in the direction D2 along the fourth pole **620G**, passes through the inner side of the third ring unit **510G** in the direction D2, turns and crosses over the outer side (direction D3 side) of the third ring unit **510G** in the direction D1 (56). Thereafter, the tip **21G** moves in the direction D1 along the fourth pole **620G**, crosses over the uppermost portion of the fourth pole **620G** in the direction D4 (57), moves in the direction D2 along the fourth pole **620G** and the third pole **520G**, and crosses over the outer side (direction D4 side) of the third ring unit **510G** in the direction D2 (58). In this state, the lace **20G** is entangled with the first pole **220G** (the fourth pole **620G**) and the third pole **520G**.

As shown in (H) of FIG. 21, the tip **21G** of the lace **20G** crosses over the outer side (direction D4 side) of the third ring unit **510G** in the direction D1 (59), moves in the direction D1 along the third pole **520G** and the fourth pole **620G**, and crosses over the uppermost portion of the fourth pole **620G** in the direction D3 (60). Thereafter, the tip **21G** moves in the direction D2 along the fourth pole **620G**, crosses over the second ring unit **310G** in the direction D3,

and crosses over the outer side (direction D3 side) of the first ring unit **210G** in the direction D2 (61), so that the lace **20G** is in a state of being entangled only with the second pole **320G** (a state in which the puzzle is solved). In this state, only the second pole **320G** exists at the inner side of the lace **20G**.

6. Sixth Embodiment

Wisdom ring puzzles **10H** and **10J** according to the sixth embodiment will be described with reference to FIG. 22A. FIG. 22A is a diagram illustrating a structure of a wisdom ring puzzle according to an embodiment of the present invention. As in the first to fifth embodiments, the wisdom ring puzzles **10H** and **10J** are puzzles using laces **20H** and **20J**. The player enjoys the wisdom ring puzzles **10H** and **10J** by entangling the laces **20H** and **20J** with poles (for example, a first pole **220H** and a second pole **320J**) arranged on the wisdom ring puzzles **10H** and **10J** or by removing the laces **20H** and **20J** from the poles.

The wisdom ring puzzle **10H** in FIG. 22A is similar to the wisdom ring puzzle **10** in FIG. 1A, and the wisdom ring puzzle **10J** in FIG. 22B is similar to the wisdom ring puzzle **10A** in FIG. 1B. In the following description, the description of the configuration similar to that of the wisdom ring puzzles **10** and **10A** of the first embodiment will be omitted. In the following description, in the case of describing the same configuration as that of the wisdom ring puzzle **10** among the wisdom ring puzzle **10H**, the description thereof may be omitted by adding the letter "H" after the symbols shown in FIG. 1A. Further, in the case of describing the same configuration as the wisdom ring puzzle **10A** among the wisdom ring puzzle **10J**, the description may be omitted by adding "J" instead of the letter "A" after the symbols shown in FIG. 1B.

[6-1. Structure of Wisdom Ring Puzzle **10H**]

As shown in FIG. 22A, the wisdom ring puzzle **10H** includes a stage **100H**, a first structure body **200H**, and a second structure body **300H**.

The first ring unit **210H** is positioned in the direction D1 with respect to the stage **100H**. The second ring unit **310H** is positioned in the direction D1 with respect to the first ring unit **210H**. As described above, in the present embodiment, the first virtual plane on which the first ring unit **210H** is arranged is substantially parallel to an upper surface **101H**, and the second virtual plane on which the second ring unit **310H** is arranged is substantially orthogonal to the upper surface **101H**. However, the present invention is not limited to the above configuration. For example, the angle formed by the upper surface **101H** and the first virtual plane may be smaller than the angle formed by the upper surface **101H** and the second virtual plane.

The first pole **220H** extends from a connection part with the first ring unit **210H** in the direction D1, passes through the inner side of the second ring unit **310H**, passes through the inner side of the first ring unit **210H** in the direction D2, and is connected to the stage **100H**. In a plan view, the first pole **220H** extends in the direction D3 from the connection part with the first ring unit **210H**, passes through the inner side of the second ring unit **310H**, and is connected to the stage **100H** at the inner side of the first ring unit **210H**. The second pole **320H** extends from the second ring unit **310H** in the direction D2, passes through the inner side of the first ring unit **210H**, and is connected to the stage **100H**.

[6-2. Structure of Wisdom Ring Puzzle 10J]

As shown in FIG. 22B, the wisdom ring puzzle 10J includes a stage 100J, a first structure body 200J, and a second structure body 300J.

The second pole 320J extends in the direction D1 from an end portion of the second ring unit 310J in the direction D1, turns and extends in the direction D2. The second pole 320J extending in the direction D2 passes through the inner side of the first ring unit 210J and reaches the stage 100J. In a plan view, the second pole 320J extends in the direction D3 from a connection part with the second ring unit 310J and is connected to the stage 100J at a position crossing over the first pole 220J and at the inner side of the first ring unit 210J.

The wisdom ring puzzle 10H shown in FIG. 22A corresponds to a configuration in which the third structure body 400 is omitted from the wisdom ring puzzle 10 shown in FIG. 1A. The wisdom ring puzzle 10J shown in FIG. 22B corresponds to a configuration in which the third structure body 400A is omitted from the wisdom ring puzzle 10A of FIG. 1B.

[6-3. Method of Solving Wisdom Ring Puzzle 10H]

A method of solving the wisdom ring puzzle 10H shown in FIG. 22A is similar to the method of solving the wisdom ring puzzle 10 shown in FIG. 1A. For example, the wisdom ring puzzle 10H can be solved in the same manner as in (A) of FIG. 2 to (D) of FIG. 2, or in the same manner as in (A) of FIG. 3 to (D) of FIG. 3.

[6-4. Method of Solving Wisdom Ring Puzzle 10J]

The method of solving the wisdom ring puzzle 10J shown in FIG. 22B is similar to the method of solving the wisdom ring puzzle 10A shown in FIG. 1B. For example, the wisdom ring puzzle 10J can be solved in the same manner as in (A) of FIG. 4 to (D) of FIG. 4, or in the same manner as in (A) of FIG. 5 to (E) of FIG. 5.

7. Comparative Example (Structure which does not Work as Wisdom Ring Puzzle)

A comparative example 1100 with respect to the present embodiment will be described with reference to FIG. 23. FIG. 23 is a diagram showing a structure of a wisdom ring puzzle in a comparative example. Although the configuration shown as a comparative example in FIG. 23 is similar to the configurations of the first to sixth embodiments described above, the configuration does not work as a wisdom ring puzzle.

Although a structure body 30V shown in (A) of FIG. 23 is similar to the wisdom ring puzzle 10H of FIG. 22A, it is different from the wisdom ring puzzle 10H in that a first pole 220V is connected to a stage 100V crossing over the outer side of a first ring unit 210V without passing through the inner side of the first ring unit 210V. The structure body 30V does not work as a wisdom ring puzzle because a sealed space is formed by a first structure body 200V and a second structure body 300V.

Although structure bodies 30W and 30X shown in (B) of FIG. 23 and (C) of FIG. 23 are similar to the wisdom ring puzzle 10J of FIG. 22B, they are different from the wisdom ring puzzle 10J in that second poles 320W and 320X cross over the outer side of the first ring unit 210 and are connected to stages 100W and 100X without passing through the inner side of first ring units 210W and 210X. The structure bodies 30W and 30X do not work as a wisdom ring puzzle because a sealed space is formed by first structure bodies 200W and 200X and second structure bodies 300W and 300X.

Although a structure body 30Y shown in (D) of FIG. 23 is similar to the wisdom ring puzzle 10 of FIG. 1A, it is different from the wisdom ring puzzle 10 in that a member passing through the inner side of a third ring unit 410Y is not a first pole 220Y between a first ring 210Y and a stage 100Y but the first pole 220Y between a connection part between the first ring unit 210Y and the first pole 220Y and second ring unit 310Y. The structure body 30Y does not work as a wisdom ring puzzle because a sealed space is formed by a first structure body 200Y, a second structure body 300Y, and a third structure body 400Y.

Although a structure body 30Z shown in (E) of FIG. 23 is similar to the wisdom ring puzzle 10A of FIG. 1B, it is different from the wisdom ring puzzle 10A in that a member passing through the inner side of a third ring unit 410Z is not a first pole 220Z between a first ring 210Z and a stage 100Z but the first pole 220Z between a connection part between a second ring 310Z and a second pole 320Z and the first ring 220Z. The structure body 30Z does not work as a wisdom ring puzzle because a sealed space is formed by a first structure body 200Z, a second structure body 300Z, and a third structure body 400Z.

The method of solving the wisdom ring puzzle shown in the above-described embodiment is merely an example, and there are various methods other than the above.

Each of the embodiments described above as the embodiment of the present invention can be appropriately combined as long as no contradiction is caused. Further, the addition, deletion, or design change of components, or the addition, deletion, or condition change of process as appropriate by those skilled in the art based on each embodiment are also included in the scope of the present invention as long as they are provided with the gist of the present invention.

Further, it is understood that, even if the effect is different from those provided by each of the above-described embodiments, the effect obvious from the description in the specification or easily predicted by persons ordinarily skilled in the art is apparently derived from the present invention.

According to an embodiment of the present invention, it is possible to provide a wisdom ring puzzle capable of sustaining the interest and motivation of a player to create a solution.

What is claimed is:

1. A wisdom ring puzzle comprising:
a stage;
a first ring unit positioned in a first direction with respect to the stage;
a second ring unit positioned in the first direction with respect to the first ring unit;
a first pole
connected to the first ring unit,
extending in the first direction from the first ring unit,
turning and extending in a second direction opposite to
the first direction,
connected to the stage passing through the inner side of
the first ring unit, and
passing through the inner side of the second ring unit at
a side of the first direction of the first ring unit; and
a second pole connected to the second ring unit and
connected to the stage through the inner side of the first
ring unit.

2. The wisdom ring puzzle according to claim 1,
wherein
the second pole extends toward the stage from an end
portion of the second ring unit in the second direction,
and
the second pole is connected to the stage.

39

3. The wisdom ring puzzle according to claim 2,
further comprising:
a third ring unit positioned between the stage and the first
ring unit; and
a third pole connected to the third ring unit and connected 5
to the stage,
wherein the first pole is connected to the stage through the
inner side of the third ring unit.
4. The wisdom ring puzzle according to claim 1,
further comprising:
a third ring unit positioned in the first direction with 10
respect to the first ring unit;
a fourth ring unit positioned in the first direction with
respect to the third ring unit;
a third pole
connected to the third ring unit,
extending in the first direction from the third ring unit,
turning and extending in the second direction, and
passing through the inner side of the third ring unit and 15
the inner side of the first ring unit; and
a fourth pole connected to the fourth ring unit and
connected to the stage through the inner side of the
third ring unit,
wherein
the first pole passes through the inner side of the second 20
ring unit, and
the third pole passes through the inner side of the fourth
ring unit.
5. The wisdom ring puzzle according to claim 1,
further comprising:
a third ring unit positioned in the first direction with 25
respect to the first ring unit;
a fourth ring unit positioned in the first direction with
respect to the third ring unit;

40

- a third pole
connected to the third ring unit,
extending in the first direction from the third ring unit,
turning and extending in the second direction, and
passing through the inner side of the third ring unit; and a fourth pole
connected to the fourth ring unit,
extending in the first direction from the fourth ring unit,
turning and extending in the second direction, and
connected to the stage through the inner side of the 10
third ring unit and the inner side of the first ring unit,
wherein
the first pole passes through the inner side of the second
ring unit, and
the third pole passes through the inner side of the fourth
ring unit.
6. The wisdom ring puzzle according to claim 1,
wherein
the second pole
extends in the first direction from an end portion of the
second ring unit in the first direction,
turns and extends in the second direction, and
is connected to the stage through the inner side of the 15
first ring unit.
7. The wisdom ring puzzle according to claim 6,
further comprising:
a third ring unit positioned between the stage and the first
ring unit; and
a third pole connected to the third ring unit and connected 20
to the stage,
wherein the second pole is connected to the stage through
the inner side of the third ring unit.
